RECORD CONTROLLED COMPUTING
MACHINE

Arthur H. Dickinson, Greenwich, Conn., assignor
to International Business Machines Corpora-
tion, New York, N. Y., a corporation of New
York

Application April 12, 1944, Serial No. 530,588

9 Claims. (Cl. 235—61.6)

This invention relates to computing machine and more particularly to the type controlled by perforated records and which is capable of selectively performing dividing, multiplying, or combined dividing and multiplying computing operations, such as, represented by the equation

$$\frac{A \times B}{C}$$

The main object of the invention is to provide a selecting means comprising distinctively perforated controlled records which precede other records which are to control the selected computation. In the present invention such control records are characterized for the purpose of distinction as "master cards" and the following computing control cards or records as "detail cards."

A more specific object of the invention is to provide a record handling, feeding and record analyzing means which will select under control of the master records the desired computing mechanism and accordingly condition the machine for the desired computation effected under control of the following detail cards.

A still further object of the invention is to provide for feeding one or more detail cards after a master card has selected the desired type of computation and retained the machine in the condition it has been put in for effecting the kind of computation determined by the master card, so that the desired computing operation can be effected as long as detail cards follow but terminate upon the sensing of the following master card.

A further object of the invention is to provide a novel setup means for the desired form of computation which is concurrently set up in the record feeding operation that a detail card is fed, to provide for the retention of the setup while the computing operation is being effected under control of one or more detail cards so that immediately upon terminating computing operation for the last detail card the next computing operation can be immediately effected.

In the present machine the distinctively perforated master records possess only the function of selecting the desired form of computation, whereas the detail cards are perforated to represent the data to control the selected computation. Inasmuch as the master and detail cards are passed through the machine in the sequence in which they are placed in the magazine and through a common feeding mechanism it is desirable to pass the master cards through the

punching machine without, however, effecting any result recording operations.

A still further object of the invention is the provision of means to run the master cards through the record handling part of the computing machine, then idly through the record punching machine so that after being ejected from the punching machine the master and detail cards are placed in the hopper of the punching machine in the same sequence in which they are initially located in the magazine hopper of the computing machine.

A still further object of the invention is to provide a plurality of computation selecting set-up means associated with a single control column of the master records and which are selectively set up to determine the type of computation to be effected under control of the following detail cards. The arrangement provides for the breakdown of the setup so that upon occurrence of the next master card requiring the same computing operation as the preceding card the associated setup means may again be set up. A breakdown is so arranged that as the master cards vary computing operations may accordingly change from master card to master card.

Other objects of the invention will be pointed out in the following description and claims and illustrated in the accompanying drawings, which disclose, by way of example, the principle of the invention and the best mode which has been contemplated, of applying that principle.

In the drawings:
Figs. 1 and 1a taken together with Fig. 1a to the right of Fig. 1 show a somewhat diagrammatic view of the various units of the machine and the drive therefor.

Figs. 2a to 2h inclusive, taken together show the complete circuit diagram of the machine when arranged according to the diagram of Fig. 3.

Fig. 3 is a diagram (on the sheet showing Fig. 1a) indicating the manner of assembly of Figs. 2a-2h comprising the wiring diagram.

Fig. 4 is a timing diagram showing the timing of the various CC cams.

Fig. 5 is a timing diagram of the FC cams.

Fig. 6 is a timing diagram of the XC cams.

Fig. 7 is a sequence diagram indicating the cyclic operations of the machine when multiplying, dividing and

$$\frac{A \times B}{C}$$

computations are successively effected, the computing mechanisms being selected by the asso-

iated master card and following detail cards controlling the selected computation.

Fig. 8 is a diagram of the plugboard connections made to effect the A, B and C entries and also the plugboard connections made to effect the selection of the different computing means under master card control.

Fig. 9 is a flow diagram showing the manner of entering factors of a multiplying computation and how the machine performs such multiplication.

Fig. 10 is a flow diagram showing the manner of entering factors of a dividing computation and how the machine performs a dividing computation.

Fig. 11 is a flow diagram showing the manner of entering factors of a

$$\begin{array}{r} A \times B \\ \hline C \end{array}$$

computation and how the machine performs the computation according to this equation.

Fig. 12 is a sectional view of the card feeding and analyzing structure.

Fig. 13 is a sequence diagram showing the occurrence of events when repeat multiplication is effected under control of a successive detail card.

1. Machine drive

Referring first to Figs. 1 and 1a, in general the machine comprises five accumulating units which are respectively designated SP, LQ, RD, ML, and MP. It may be explained that the unit ML contains accumulators and readouts from which all of the nine digital multiples of the divisor or multiplicand can be derived depending upon whether the machine is used for division, multiplication, or

$$\begin{array}{r} A \times B \\ \hline C \end{array}$$

computation. The MP receiving device receives the multiplier upon entry in the multiplying or

$$\begin{array}{r} A \times B \\ \hline C \end{array}$$

calculation. Such unit is not utilized in a dividing computation of

$$\begin{array}{r} B \\ \hline A \end{array}$$

The accumulating units LQ and RD receive components of the products upon multiplication with the final product formed in LQ, and upon division or

$$\begin{array}{r} A \times B \\ \hline C \end{array}$$

computation LQ receives the quotient amount. In division RD receives the dividend amount, and in

$$\begin{array}{r} A \times B \\ \hline C \end{array}$$

computation RD receives the product of A $\times$ B. The SP unit is utilized in receiving the "C" factor of a

$$\begin{array}{r} A \times B \\ \hline C \end{array}$$

computation. The various accumulating units are driven by the gearing delineated from the driving motor M. The machine is also provided with a direct current generator DC. The card handling and feeding section of the machine is

of customary form like that shown in Daly Patent No. 2,045,437 and is driven in the usual manner. The FC cam contacts FC2—22 (Fig. 1a) are also driven in the customary manner in synchronism with the drive of the card handling section of the machine. The units designated CY, N—R, are electromechanical relay setup units of the general construction shown in Figs. 16 and 17 of Patent No. 2,295,448, issued to J. W. Bryce et al.

10 Each of these units is adapted for reset from the constantly running drive shaft by the customary one-revolution clutch arrangement. The reset magnets for the units are respectively designated 321CY, 321N—R. The comparing units are 15 shown diagrammatically at CU—CU. These comparing units are of the form shown in Figs. 12 to 15 inclusive of the patent to Bryce et al., No. 2,295,448, and such units are adapted to be driven from the drive shaft by the use of the well known 20 one-revolution clutch, the clutch magnet being designated 342. Also driven from the main drive shaft are the usual CC cams designated CC1—40 and the impulse distributor 306. In addition there are also provided eight impulse emitters 25 which are designated 314, 344, 414, 322, 410, 375, 348, 350 and 512.

2. Accumulators and entry receiving devices

As stated, the SP, LQ, RD, ML and MP units 30 are accumulators of electromechanical type. These accumulators are identical in construction except for the number of readout sections, some accumulators having four readout sections and others having less. The accumulator which is 35 here employed may be of various types known in the art, more particularly the type of accumulator having electrical transfer and electrical reset. Suitable accumulators of this type are shown and described in United States Patent No. 40 1,834,767 and suitable readout structure may be that shown in United States Patent No. 2,062,117 employing the electric reset of Patent No. 1,834,767, modified as per British Patent No. 422,135.

45 The present invention involves transfer total arrangements according to British Patent No. 422,135.

While the aforesaid accumulators are a suitable type for use with the present invention, a preferred accumulator is of the form illustrated 50 and described in Lake and Pfaff Patent No. 2,232,006, dated February 18, 1941.

3. Insertible plugboards

55 The insertible plugboard construction is of a type known in the art and the insertible plug unit is generally indicated at 141 in Fig. 18 of Patent No. 2,295,448. Devices of this type are generally known as "automatic plugboards" and a suitable form of such plugboard is shown and fully described in the patent to C. D. Lake, No. 2,111,118, dated March 15, 1938. Such automatic plugboard arrangement comprises a series of relatively fixed machine sockets to which the fixed machine wiring is connected. Adapted for cooperation with such sockets are plug prongs carried by a replaceable plugboard assembly or unit. Such plug prongs on the replaceable board are in 60 turn connected to plug sockets upon the replaceable board. These plugboard sockets may be in turn plugged up by the operator selectively at will or the entire board may be pre-plugged with a desired set of connections.

70 The manner in which the replaceable plugboard

unit is wired and plugged for the form of control described herein is shown in Fig. 8.

It may be explained that the plug socket reference numerals used on the circuit diagram of Fig. 2a-2h are the same as those used on the diagrammatic plugboard view of Fig. 8.

4. Cam timing diagrams

The cam timing diagrams, Figs. 4, 5 and 6 are self-explanatory. It should be noted that the cams controlling the CC cam contacts of Fig. 4 make one revolution for each machine cycle. The cams controlling the FC cam contacts of Fig. 5 when called into operation make one revolution for each card feed cycle which comprises two machine cycles. The cams controlling the XC cam contacts of Fig. 6 when called into operation make one revolution for three machine cycles.

Such XC cam contacts are driven from the drive shaft through a one-revolution clutch which is controlled by magnet 312. (Fig. 1.) The drive side of the one-revolution clutch receives its drive from the main drive shaft 50 through the gearing shown which drives the XC cams one revolution for each three revolutions of the main drive shaft.

5. Operation utilizing plugboard shown in Fig. 8

This figure shows plug connections to be made when the machine is to be set for multiplying computations $A \times B$, the

$$\begin{array}{r} A \times B \\ \hline C \end{array}$$

or

$$\begin{array}{r} B \\ \hline A \end{array}$$

computations, these being selectively performed when the master cards are significantly perforated in the control column. For simplification it will be assumed that the first master card is significantly perforated in the control column which calls for multiplying under control of the next detail card, the second master card calls for dividing under control of the next detail card, and the third master card calls for the

$$\begin{array}{r} A \times B \\ \hline C \end{array}$$

computation under control of the following detail card.

6. Multiplying

The operation of the machine will first be explained with reference to multiplying. In explaining multiplying the manner in which multiples of an entered amount are built up and stored in the machine will be set forth but these multiple building up operations are equally applicable to the building up of the divisor in dividing computations and in the

$$\begin{array}{r} A \times B \\ \hline C \end{array}$$

computation.

Before describing multiplying operations it may be stated that the circuit diagram of the instant application has been shown with a certain columnar capacity. For simplicity of illustration the capacity as shown by the circuit diagram is two columns by two columns, but it will be appreciated that in actual practice the machine may have a greater columnar capacity. Greater columnar capacity is derived primarily by a duplication of orders of accumulators, readouts, and increased number of entry circuits.

It will be assumed that a set of master and following detail record cards are in place in the supply magazine of the machine. The operator then closes switch 300, supplying current to driving motor M (Fig. 2b). With the main driving motor M in operation the D. C. generator marked "DC" (Fig. 2d) is set in operation supplying current to ground and to D. C. line 301. The operator now depresses start key 302 (Fig. 2d) and a circuit is completed from ground through the FC3 contacts through relay contacts F1, through the start key contacts back through relay coil E to line 301. Relay coil E upon being energized is maintained energized by a stick circuit through relay contacts E1 and cam contacts FC2. The energization of relay coil E closes relay contacts E2 and a circuit is completed from ground, through cam contacts CC29, through the punch controlled contacts P1 (Fig. 2d) and the E2 contacts now closed, through the JJ2 contacts, through the stop key contacts 303 now closed, through the card feed clutch magnet 304, back through the D1 contacts in the position shown to line 301. A master card is now fed by the card feeding and handling section of the machine (Fig. 12). During the first card feed cycle the first master card will be fed to be analyzed by the presensing brushes 371 to determine the computation to be performed in a manner to be subsequently explained. It is explained here that the presence of a perforation in the "9" position of a control column will enable the machine to remain in its normal status for effecting a multiplying operation of $A \times B$ under control of the following detail card. In starting up the machine on a run of cards, the start key must be maintained depressed for two card feed cycles or it may be depressed and released and then redepressed. During the first card feed cycle certain idle operations occur which may be merely alluded to. The RD accumulator is reset to zero and circuits of the machine are conditioned just as if a product amount were to be punched. Punching does not occur at this time, however, because there is no result to record and the card has not yet reached the punching machine.

Upon redepression or maintained depression of the start key 302 (Fig. 2d) the previously described circuit will be established to the card feed clutch magnet 304 and a second card feed cycle will ensue during which the master card will be fed past the analyzing brushes 308 and a following detail card will be fed from the magazine hopper to the brushes 371 and in such position that in a subsequent or third card feed cycle amounts from the following detail card will be read by the analyzing brushes 308 to effect entries to control the selected computation. However, in the feeding of the master card past the analyzing brushes 308, no analysis of the master card occurs thereby, since the master cards carry only the computing selecting perforations which are not analyzed by brushes 308. As will be later evident, means is set in operation by the master card to render such entry means effective prior to a computation.

During the second card feed cycle, the master card is fed past the analyzing brushes 308 to the punch tray in the usual manner. Upon reaching this tray, card lever contacts 311 (Figs. 2d and 12) close to energize the relay coil D. The energization of relay coil D shifts relay contacts D1, (left side of Fig. 2d) to a reverse position from that shown, cutting off the current supply to the card feed clutch magnet 304 and providing current supply for the punch rack trip mag-

net 318 upon closure of cam contacts CC1 with contacts P3 and relay contacts B1 closed. The relay contacts B1 become closed upon energization of the B relay coil (Fig. 2d, lower left side) upon closure of the customary last column punching contacts P5. With punch rack trip magnet 318 energized, contacts 319 (Fig. 2b) become closed and remain latched closed in the customary manner by latch 320. Current supply is then provided for the punch driving motor PM and endwise card feed occurs during the two subsequent machine cycles in the usual way to feed the card to the first computation result punching position. Inasmuch as there is no result to be punched, this operation in the punching machine is an idle one.

7. LQ Reset

With relay coils B and D energized in the manner previously explained, relay contacts B2 and D2 (Fig. 2e) become closed. Upon closure of cam contacts CC21, current will flow from the 301 line through these contacts through the relay contacts AK2 now in the position shown, down through the now closed B2 contacts, the HH2 contacts now closed, the D2 contacts now closed to and through the 321LQ reset relay coil to ground. Reset will then be effected of the LQ accumulator during a machine cycle following the second card feed cycle.

The present machine employs electric reset and provision is accordingly made to maintain the 321LQ relay coil energized during the reset cycle. This is provided for by stick contacts LQ1, such contacts being in a stick circuit including cam contacts CC5. Upon energization of the LQ relay, contacts LQ2, LQ3-6 (Fig. 2h) and LQ7 (Fig. 2g) shift to reverse position from that shown. With LQ2 (Fig. 2h) in reverse position current supply is afforded to an emitter 322 which is wired in a nines complementary manner to the LQR readout. Complemental impulses representative of the nines complement of the amount standing in LQ flow through the now shifted LQ3-6 contacts, through the set of lines generally designated 323 to the 313LQ accumulator magnets and back to ground (see also Fig. 2g). By thus introducing the nines complement of the amount standing in LQ the accumulator elements are restored to a 9 position. To bring the accumulator to zero from the all 9 position, an elusive 1 is entered in the units order at the carry time in the cycle. This entry is provided through the contacts LQ1 which are closed in the manner previously explained. This impulse is supplied in the following manner: From line 301, through cam contacts CC16, (Fig. 2g) via line 324, through the LQ1 contacts, through the normal carry relay contacts AV4 controlled by relay coil AV (Fig. 2d) down to the units order of the 313LQ magnets. The units order is thus advanced one step and the electric transfer devices of the accumulator cause advance of all the other higher orders one step.

It may be explained that as long as the machine is operating, cam contacts CC2 close once each machine cycle at the carry time in the operation of the accumulators. Such closure of cam contacts CC2 energizes relay coil AV (Fig. 2d). The energization of coil AV closes contacts AV1-4, and AV5-9 (Fig. 2g), AV10-11, (Fig. 2e), AV12-28 (Fig. 2a) and AV29-30 (Fig. 2c), which are respectively associated with the LQ, RD, MP, ML and SP accumulators. Since coil AV becomes energized once each machine cycle the

aforementioned relay contacts thus close at the carry time. The closure of these contacts permits the electric carry devices to be effective for performing carry operations whenever they are required in their related accumulators.

During LQ reset, provision is made to prevent repetition of such reset. This repeat reset preventing means is provided for as follows: During LQ reset, the LQ8 contacts are closed (Fig. 2d right side). Accordingly, when cam contacts CC6 close, a circuit is provided from ground through the LQ8 contacts, through CC6, either through relay contacts AK3 or through the AN3 contacts to relay coil HH. Relay coil HH, becoming energized, establishes its stick circuit through contacts HH1 and the punch controlled contacts P2 now closed. On Fig. 2e, the relay contacts HH2 open and thus interrupt the reset initiating circuit to 321LQ.

8. Master card control of multiplying mechanism

Reverting to operations performed in the first card feed cycle upon starting up the machine, it will be assumed that the first master card fed 25 from the magazine hopper to be analyzed by the brushes 371 is perforated at the 9 index point position of the control column which calls for a multiplying computation to be effected under control of the following detail card. Referring 30 to Fig. 2h a circuit will be completed in the second machine cycle of the first card feed cycle from line 301, through the FC15 cam contacts, conductor plate 370, analyzing brush 371 in a column to sense the "9" index point position of the control column, GA1 relay contacts, to the emitter 512 which when it makes at the time the "9" index point is analyzed by brush 371 causes an impulse to flow to plug hub 501, via plug connection from plug hub 501 to plug hub 515, (see 40 also Fig. 8) to grounded relay coil EA. Relay coil EA energizes to close its stick contacts EA1, the stick circuit extending back through EA1 contacts to the cam contacts FC19 contacts. The latter maintains the energization of the relay coil 45 EA to the end of the first card feed cycle and for substantially half of the first machine cycle of the second card feed cycle. This second card feed cycle, it will be recalled, is initiated manually and during the first machine cycle of the 50 second card feed cycle while the EA relay is energized cam contacts FC20 close and with the EA2 contacts now closed a circuit will be closed from line 301 through cam contacts FC20, through EA2 contacts to the grounded FA relay coil. A 55 stick circuit for the FA relay coil is provided back through the FA1 contacts and the punch control contacts P2a, the latter being operated concurrently with the P2 contacts (Fig. 2d). By this stick circuit FA relay will be retained energized 60 during the remainder of the second card feed cycle and during the subsequent two machine cycles during the first of which the LQ accumulator is reset in the manner previously described. During the second machine cycle there is a reset 65 of the ML and MP receiving devices provided for by the following circuit.

9. Reset of ML and MP receiving devices

During the LQ reset cycle, while the 321LQ 70 relay coil is retained energized to close the LQ11 and LQ12 relay contacts (Fig. 2f) cam contacts CC24 close, thereby closing a circuit from the line 301, through cam contacts CC24, FA5 relay contacts now closed, then through LQ11 relay 75 contacts now closed through the grounded KK

relay coil. A branch circuit also extends from the FA5 relay contacts through the LQ12 relay contacts to the H grounded relay coil.

Upon energization of coils H and KK, these coils are maintained energized by stick contacts H1 and KK1, respectively, the stick circuit extending back through the ML5 contacts to line 301. The energization of relay coils H and KK will cause closure of relay contacts H3 and KK2 (Fig. 2e) and upon closure of cam contacts CC27 current will flow from the line 301 through cam contacts CC27, through the AK2 relay contacts now in the position shown, through the H3 contacts, through the KK2 contacts, through the AK17 contacts now in the position shown, through the 321MP reset relay and also through the 321CY reset magnet. A branch circuit is also completed to energize the CA transfer coil. The coils 321CY, 321MP and CA are maintained energized by a stick circuit through contacts MP4 and CA4, through cam contacts CC5 back to line 301.

In order to reset the multiplicand multiple receiving devices, 321ML reset relay is energized. This magnet is energized in the following manner: At the time the KK2 and H3 contacts close a branch circuit will be extended through the 321ML reset relay. Upon energization of this relay the ML1 contacts close to provide a stick circuit for coil 321ML. The return circuit to line 301 extends through cam contacts CC5.

10. Skipping master card idly through punching machine

Reverting to operations performed in the LQ reset cycle, relays FB and FC (Fig. 2d, right side) are energized at the beginning of this cycle when cam contacts CC37 close, it being understood that at this time the LQ13 contacts and the FA2 contacts are now closed. The energizing circuit is from ground through cam contacts CC37, LQ13 relay contacts now closed, through FA2 contacts now closed, to the FB relay coil, to line 301. A branch circuit also extends from the LQ13 contacts through FA3 relay contacts now closed to the FC relay coil. Independent stick circuits are provided for such relays and the stick circuit for the FB relay coil is through the FB1 stick contacts and the B3 relay contacts, whereas for the FC relay the stick circuit extends to the FC1 contacts and the P2 punch contacts. The B3 contacts are controlled by the B relay coil which, it will be recalled, is controlled by the last column contacts P5. After the master card has been skipped through the punching machine the card carriage arrives at the last column position and P5 contacts open to deenergize the B relay. The latter opens its B3 relay contacts to break the stick circuit of the FB relay.

The FB relay coil transfers the FB4 contacts and closes the FB2 (Fig. 2d, left side) contacts. When the FC relay is deenergized as a result of the opening of the punch contacts P2 upon arrival of a card at the first column punching position, relay coil FC will deenergize and the FC2 contacts will close, it being understood at this time that the FB2 contacts are still closed. This will complete a circuit to transmit an initial impulse to the punch magnet 360 which is from the line 301, through the punch magnet 360, the FB2 contacts now closed, FC2 contacts now closed, through the so-called floating cam contacts 358, thence through the now transferred FB4 contacts to ground. This initial impulse to the punch magnet 360 will cause an idle step of move-

ment of the punch carriage resulting in the opening of floating cam contacts 358 as is well known. When the carriage comes to rest after having escaped to the next column, contacts 358 then close to transmit a second impulse to the punch magnet 360. As is well known, a repetition of such impulses to the punch magnet 360 will occur to skip the master card through the punching machine without effecting any punching operations until the last column position is reached, at which time the last column contacts P5 close. This causes the energization of the B relay coil and the opening of the B3 contacts to deenergize the FB relay, thus normalizing the punching circuits.

The aforescribed operation through the punching machine occurs during two idle cycles of the computing machine and upon completion of such skipping operations a third card feed cycle is initiated by the following described circuit:

10. Initiation of card feed cycle with a concurrent XC cycle

25 A third card feed cycle is initiated upon completion of the second of the two idle cycles during which time the master card is skipped through the punching machine.

During the ML reset cycle the ML24 relay contacts (Fig. 2d) become closed upon energization of relay coil 321ML and upon closure of cam contacts CC20 a circuit is established from ground through cam contacts CC20, ML24 relay contacts now closed, through relay coil E to line 301. Relay coil E is held energized by a stick circuit directed through the E1 relay contacts and cam contacts FC2. Energization of the E relay coil during the ML reset cycle closes contacts E2 to condition the impulse circuit for the card feed clutch magnet 304 for subsequent energization. During the skipping of the master card the P1 punch contacts (Fig. 2d, left side) close and when cam contacts CC29 close at the end of the cycle during which completion of the skipping of the master card has been effected, a circuit is closed from ground, through cam contacts CC29, P1 punch contacts now closed, E2 relay contacts now closed, JJ relay contacts now closed, stop key contacts 303, card feed clutch magnet 304, D1 relay contacts now in the position shown to line 301. A new or third card feed cycle now ensues.

11. Rotation of XC cams

55 A concurrent energization of the clutch magnet 312 is also effected so as to release for rotation the group of XC cams which rotate one revolution for three subsequent machine cycles. This branch circuit extends from the stop key contacts 303, through the AE4 relay contacts now in the position shown, thence through the G2 relay contacts now closed, through the EC5 relay contacts, EB5 relay contacts, EA4 contacts now closed to the supplemental clutch magnet 312. The rotation of such cams renders effective the entry mechanism under control of the following detail cards so that amounts represented thereon may be entered in the machine for controlling the selected computation.

12. RD reset

In order to reset the RD accumulator the following control circuits are provided: Referring to Fig. 2e, upon closure of cam contacts FC14 during the reinitiated card feed cycle, a circuit is established from line 301, through cam contacts

FC14 now closed, through the DA7 contacts now closed, through the AK19 contacts now in the position shown, through the now closed A14 contacts, to the 321RD reset coil.

Energization of 321RD closes stick contacts RD1, the stick circuit being completed back to line through cam contacts CC5. Energization of 321RD as above explained causes the shift of contacts RD2 (Fig. 2g) and a shift of contacts RD4-7. With such contacts shifted a circuit is established from line 301 (Fig. 2c), via wire 347 (see also Fig. 2g) to and through the DD5 contacts in the position shown, through the now shifted RD2 contacts to emitter 350. Emitter 350 is a nines complementary emitter and with current supplied to it, nines complementary impulses are emitted through RDR and through the now shifted RD4-7 contacts to a set of lines generally designated 351. The impulses flow via these lines and lines 513 to the 313RD accumulator magnets and advance the accumulator elements to an all 9 position. Thereafter, a carry impulse is introduced into the units order of the accumulator through the closed RD3 and AV9 contacts which establish a circuit from the carry impulse line 324 to the 313RD accumulator magnet in the units order. The customary electric transfer contacts in the accumulator afford carry into the higher orders of the accumulator so that all accumulator elements are brought back to a zero status.

13. Analysis of amounts on detail card

Late in the first machine cycle of the first card feed cycle the card lever contacts 305 close, bringing about an energization of relay coil G. (Fig. 2d.) Energization of relay coil G brings about closure of relay contacts G1 (Fig. 2e) which are retained closed as long as cards feed to afford a current supply to the FC6 contacts. These cam contacts upon closure permit current to be supplied to the impulse distributor 306 from which current impulses flow to the card feed and contact roll 307. The usual regular analyzing brushes 308 are provided which are connected to plug sockets generally designated 309.

During the second card feed after the G relay has been energized, controls are set up to cut off the start key control circuit and to also maintain the operation of the machine under record card control. Referring now to Fig. 2d, early in the entry cycle cam contacts FC4 close, energizing relay F. F being energized, it is maintained energized by a stick circuit which is completed through contacts F1 and cam contacts FC3. The shift of the F1 contacts cuts off the circuit to the start key contacts 302. Energization of F closes contacts F2 to maintain a stick circuit for relay coils F and G either through FC3 or the card lever contacts 305.

During the third card feed cycle the detail card passes between the brushes 308 and contact roll 307 and the MC and MP, or A and B amounts on the detail card are analyzed and entered in the respective accumulators. (See Fig. 7.) During the entry portion of this XC cycle, cam contacts XC1 close to energize relay coil K (Fig. 2d). With relay coil K energized, the K1-8 contacts (Fig. 2a) become closed. The multiplicand amount is entered under control of the related analyzing brushes 308, plug connections between plug sockets 309 and the 311 plug sockets (Figs. 2a and 8) through the WW1-2 contacts, down through the now closed K1-8 contacts. The amount of the multiplicand is entered into the

following multiple receiving devices ML1-2, ML3-6, ML5, ML7 and ML9. On the circuit diagram the prefix reference numeral 313 refers to the accumulator magnets of these multiple receiving devices.

At this point it may be explained that the multiple receiving devices are commonly used for both multiplying operations and for dividing operations. On multiplication, these multiple receiving devices are used to build up and store nine different multiples of the multiplicand and on division the same multiple receiving devices are used to store nine different multiples of the divisor. The multiple receiving devices have been previously described; these are in the form of electrically controlled accumulators with electrical readouts. The ML1-2, ML3-6 and ML4-8 receiving devices are provided with doubling readouts in addition to the usual straight readouts. The other multiple receiving devices are provided with straight readouts only. On the entry portion of the feed cycle, as explained, the amount of the multiplicand or "A" amount, is entered into five of the multiple receiving devices concurrently.

Before describing how the multiples of the multiplicand are built up, it may be stated that the multiplier or B amount is entered in the following manner. The multiplier enters under control of the related analyzing brushes 308, through plug connections between plug sockets 309 and plug sockets 310 (Figs. 8 and 2e) through the DA4-5 contacts now in the position shown through the MP1-2 contacts now in the position shown, to the 313MP accumulator magnets and to ground. The amount of the multiplier is thus entered into the multiplier receiving device.

Coincidentally with this setup of the multiplier in the multiplier receiving device there is a setup of the cycle controller and this setup is made according to the presence of significant digits in the multiplier amount. Assuming 27 to be the amount of the multiplier, at the "7" index point in the cycle, the grounded ADu relay (Fig. 2e) coil is energized and at the "2" index point the grounded ADt relay coil is energized. "u" and "t" refer to the units and tens columnar orders.

14. Building up of multiples

It has been previously explained that on the entry cycle, the multiplicand amount was entered into ML1-2, ML3-6, ML5, ML7 and ML9. On the machine cycle following the entry cycle, there occurs the first step in the building up of further multiples. (See Fig. 7.) As stated, the ML1-2 device is provided with a doubling readout. This is designated MLR1-2 on Fig. 2b. In this machine cycle cam contacts XC2 (Fig. 2d) close, energizing relay coil L. With relay coil L energized, relay contacts L1-12 (Fig. 2a) close and current supply is afforded for the adding emitter 314 as follows: From line 301 (Fig. 2b), through contacts MM1, and ML2 in the position shown, thence to emitter 314. From emitter 314 the impulses flow over to the transverse buses of the doubling section of MLR1-2, down through the piloting section of this readout and out via a group of lines generally designated 315. From these lines the impulses flow down through the L1-12 contacts (Fig. 2a) which are now closed and ultimately reach the ML3-6, ML4-7, ML5 and ML9 accumulators or multiple receiving devices. This operation will have completed the building up of the 3 multiple in ML3-6.

On the following machine cycle, the cam contacts XC3 (Fig. 2d) close, energizing relay coil

M and causing closure of contacts M1—12 (Fig. 2a). With the emitter 314 in operation the times 2 multiple of the multiplicand is read out from MLR1—2 and flows via lines 315 and through the M1—6 contacts to the ML4—8 and the ML5 accumulators. This will have completed the setting of the 4 and 5 multiples on these receiving devices. During the same cycle in which these entries are being made, the 6 multiple of the multiplicand is read out from the doubling readout section of MLR3—6 and such 6 multiple flows via lines 316 (Figs. 2b, 2f, 2e and 2a), through the M1—12 contacts and finally reaches the ML7 and ML9 receiving devices. This operation will have completed the setting up of the 9 multiple on ML9 and the setting up of the 7 multiple on ML7. The multiple building up operations are now complete.

During the third card feed cycle, the detail card from which the factors were read is advanced to the punch tray in the usual manner. Upon reaching this tray, the contacts 317 close (Fig. 2d) to energize relay coil D. The energization of relay coil D shifts relay contacts D1 to a reverse position from that shown cutting off current supply from the card feed clutch magnet 304 and providing current supply for the punch rack trip magnet 318 upon closure of cam contacts CC1 with contacts P3 and relay contacts B1 closed. The relay contacts B1 become closed upon energization of relay coil B upon closure of the customary last column punch contacts P6. With punch rack trip magnet 318 energized, contacts 319 become closed and remain latched closed in the customary manner by latch 320 (Fig. 2b). Current supply is then provided for the punch driving motor PM and endwise card feed of the detail card occurs in the usual way to feed the detail card to the first product punching position.

15. LQ reset

With relay coils B and D energized in the manner just explained, relay contacts B2 and D2 (Fig. 2e) become closed. Upon closure of cam contacts CC21, current will flow from the line 301 through these contacts, through the relay contacts AK2 now in the position shown, through the now closed B2 contacts, the HH2 contacts now closed, the D2 contacts now closed to and through the 321LQ reset relay coil to ground. Reset will then be effected of the LQ accumulator in the manner previously explained in section 7.

Computing operations of the machine, that is to say, the adding of selected multiples of the multiplicand into the product receiving device, are initiated by LQ reset. From the LQ8 contacts, (Fig. 2d) a branch circuit extends to contacts CC1 and upon closure of these cam contacts, relay coil JJ is energized, relay contacts H2 being now closed. JJ once being energized is maintained energized by a stick circuit through contacts JJ1, through the reset contacts ML3 and back to ground. Coil JJ is the computing initiating control.

16. Multiplying operations

With the present machine for multiplying, multiplication is effected by entering into the dual product receiving devices multiples of the multiplicand from the multiple readout devices. The selection of multiples is made under the control of the MPR readout according to the amount of the multiplier standing in the MP receiving device. Inasmuch as the multiple receiving devices

and readouts associated therewith provide all nine digital multiples of the multiplicand, it is possible to enter two multiples pertaining to two different orders of the multiplier concurrently into the separate sections of the result receiving devices. While multiple selection is afforded by the MPR readout for such concurrent entry there are supplemental entry controls afforded by the cycle controller. The cycle controller ascertains in which columns of the multiplier there are significant digits and in which columns there are zeros. Selective controls are set up in the cycle controller according to such zeros and significant digits and these controls determine which orders of MPR are to be effective for controlling multiple selection. The cycle controller also controls column shift action for routing of multiple entries to the result receiving devices in proper columnar relationship therein.

Before the cycle controller is further explained its principles of operation may be briefly set forth. If significant multiplier digits are present in all odd and even columns of the multiplier the machine will concurrently enter multiples pertaining to adjacent odd and even columns and thereafter advance to another pair of odd and even columns and make another concurrent multiple entry for these two columns. If zeros are present in any odd multiplier column, multiple entry cycles will be omitted for any such odd orders. Likewise where zeroes appear in even orders of the multiplier amount entry cycles will be omitted for such even orders. In referring to odd and even orders of the multiplier, counting of orders is commenced from the right, that is, the units is one, an odd order, and the tens is two, an even order. The cycle control for odd orders is wholly independent of the cycle control for even orders.

In the operation of the machine, both the odd order cycle controller and the even order cycle controller must both have completed their independent control of entries before further machine operations can take place.

In substance, the machine has two independent cycle controllers, one for even orders and the other for odd orders and, in effect, multiple entries. The machine may complete one set of multiple entries under the control of one cycle controller ahead of the multiple entries which are effected under the control of the other cycle controller. However, whenever possible, concurrent entries are made into both sections of the product receiving device. The only time when such concurrent entries are not made is when zeros are present in either all odd multiplier orders or in all even multiplier orders or when one cycle controller has completed its controls in advance of the other.

The entry routing controls are so arranged that multiples pertaining to odd orders of the multiplier always go to RD and multiples pertaining to even orders of the multiplier always go into LQ.

Summarizing, the machine has in effect two cycle controllers. One cycle controller derives its control from odd numbered columns of the multiplier. The other cycle controller derives its control from even numbered columns of the multiplier. Each cycle controller tries to complete its operations in the minimum number of successive machine cycles and both cycle controllers can operate concurrently. One cycle controller will direct entries into one accumulator and the other cycle controller will direct entries into the

other accumulator. In the complete wiring diagram only a dual order multiplier is utilized, but in practice, this multiplier, of course, might contain many more orders. The cycle controller is, however, here shown with provision for more than two orders in order that its principles of operation may be disclosed and understood.

Upon energization of relay coil JJ in the manner previously explained relay contacts JJ5 (Fig. 2f) close and upon closure of cam contacts CC28, a circuit is completed from line 301, through the AK5 contacts in the position shown, through CC28, through the ML4 relay contacts in the position shown, through the JJ5 contacts now closed, through 340SA and back to ground. Magnet 340SA is the magnet of a stepping switch SA. Such stepping switch may be of the general type shown in United States patent to Bohlman No. 1,569,450. Upon energization of 340SA the stepping switch arms of the cycle controller are advanced from normal off contact position to the first contact position (Fig. 2e). In Fig. 2e the first contact position is that which is in circuit with contact ADt5 and ADu5. The energization of relay coil JJ will have closed relay contacts JJ5 and upon the closure of cam contacts CC3 and CC26 current will flow from line 301, through CC3, through JJ3, through the ADu5 contacts now in closed position as brought about by the energization of the ADu magnet in the manner previously explained, down via line 326, through the column shift relay magnet CSc and back to ground. A circuit is also completed through contacts ADt5, via line 327 to the column shift relay magnet CSb and back to ground.

The energization of CSc will close its related column shift contacts CSc1—3 shown on Fig. 2g and direct the entry of the multiple related to the units order of the multiplier into the proper columns of the RD result accumulator. The energization of CSb will close its related column shift contacts CSb1—3 on Fig. 2g and direct the entry of the multiple pertaining to the tens order of the multiplier into LQ. Concurrently with the energization of the above mentioned shift magnets CSc and CSb, current supply is afforded through lines 328 and 329 to the units and tens common segments of MPR (Fig. 2f). With the problem under consideration (see Fig. 9) the multiplier amount is 27 so the brush in the units order of MPR will stand on 1 and the brush in the tens order will stand on 2. With such brushes in these positions, the 1 brush in the units order will allow current to flow to the 1X multiple selecting relay. The circuit back to ground is through the AK6 relay contacts now closed. The brush standing on the 2 spot of the tens order will permit energization of the 2XX multiple selecting relay. The respective multiple selecting relays X and XX have stick contacts such as 1X1 and 2XX1 which when closed establish stick circuits which not only maintain their related multiple selecting relays energized but also maintain the selected column shift relays energized. The stick circuit from the XX relays is via line 338, which extends back to line 301, through cam contacts CC15. The circuit to the stick contacts of the X relays is via line 331, which extends to line 301, through cam contacts CC15.

With the above mentioned multiple selecting relays energized the related contacts such as 2XX2—4 and 1X2—4 (Fig. 2b) will become closed and a readout of the 2 multiple will be permitted from the doubling section of MLR1—2 with the entry of such 2 multiple into LQ. The path of

impulse flow from the contacts 2XX2—4 is via a group of lines generally designated 332 (see Figs. 2b, 2f, 2g). Lines 332 extend to contacts AK1—9 in the position shown and the impulses will flow through these contacts through the now closed CSb1—3 column shift contacts, through the AK10—12 contacts in the position shown, to the 313LQ accumulator magnets. The 7 multiple will be read out from MLR1 and the impulses will flow through the 1X2—4 contacts over a group of lines 333 (Figs. 2b, 2f and 2g), through contacts AK39—41 and contacts DD2—4 which are in the position shown, down through the CSc1—3 column shift contacts, through the group of contacts AK13—15 in the position shown, to the 313RD accumulator magnets.

It will be understood that with the foregoing computation if the multiplicand amount is 32, the 7 multiple of that amount would be 224. The 2 multiple would be 64. Accordingly, there would be a concurrent entry of 64 and 224 respectively, into LQ and RD. (See Fig. 9.) 64 would be entered into LQ in a tens relationship. The multiplying computation so far as entry of selected multiples is concerned is now complete, but it will be understood that with a larger size machine further multiple and selecting cycles would follow. Assuming, however, that the computation is complete on the entry of two multiples for a two significant digit multiplier, the machine will now terminate multiple selecting and entering operations and controls will be conditioned for the next step of the computation. This next step involves the transfer of the amount in RD over into LQ. During this same transfer cycle there will be other operations effected as follows: The multiple receiving devices and the MP receiving device will all be reset to zero. There will also be a reset of the cycle controller set up unit. During this same cycle in which these resets take place, the stepping switch SA will be restored to its normal or non-advanced position.

Near the end of the multiple entering cycle cam contacts CC28 (Fig. 2f) reclose and again energize 340SA. The stepping switch arms (Fig. 2e) will be advanced to the second contact position. Contacts ADt4—4 and ADu4 will be in shifted position and all remaining cycle controller contacts such as ADh1—4, ADth1—4, etc., will be in non-shifted position. Upon closure of CC3 and CC26 current will flow through the JJ3 contacts now closed, through the switch arms of the stepping switch, through the ADu4 (Fig. 2e) contacts, through the lower pyramidal contacts, out via line 334, down through relay coil KK (Fig. 2f) and back to ground. Another circuit will be established through the contacts ADt4 (Fig. 2e), through the lower pyramidal contacts, through line 335, down through relay coil H (Fig. 2f). In the event that relay coils H and KK are concurrently energized, the subsequent controls are brought into action, but if one or the other of these coils H or KK is not energized and the other one is energized, the controls now to be described will not be effective.

Upon energization of coils H and KK, these coils are maintained energized by stick contacts H1 and KK1, respectively, the stick circuit extending through the ML5 contacts and back to line 301. The energization of relay coils H and KK will cause closure of relay contacts H3 and KK2 (Fig. 2e) and upon closure of cam contacts CC27 current will flow from the line 301, through the AK2 contacts now in the position shown, through the H3 contacts, through the KK2 con-

tacts, through the **AK17** contacts now in the position shown, through the **321MP** reset relay and also to the **321CY** reset magnet. A branch circuit is also completed to energize the **CA** transfer relay coil. The coils **321CY**, **321MP** and **CA** are maintained energized by a stick circuit through contacts **MP4** and **CA4** which extend to line **301**, through cam contacts **CC5**.

In order to reset the multiple receiving devices, the **321ML** reset relay is energized. This magnet is energized in the following manner: At the time contacts **KK2** and **H3** close, a branch circuit is established through the **321ML** reset relay. Upon energization of this relay the **ML1** contacts close to provide a stick circuit for coil **321ML**. The return circuit to line extends to cam contacts **CC5**.

The foregoing description has explained the manner in which **321CY** is energized. The **CY** unit (Fig. 1) is then reset in the customary manner. The description has also explained the manner of energization of relay coils **321MP** and **321ML**. Upon energization of relay coil **321MP**, the relay contacts **MP1—2** and **MP3** (Fig. 2e) shift to reverse position from that shown. Upon energization of **321ML**, the **ML6—23** contacts (Fig. 2a) and the **ML2** contacts (Fig. 2b) shift to reverse position from that shown. The shift of contacts **ML2** (Fig. 2b) places a nines complementary emitter **344** in circuit and nines complementary impulses are emitted from this emitter through the straight readout sections of the **MLR1—2**, the **MLR3—6**, **MLR4—8**, **MLR5**, **MLR7**, **MLR9** and through one section of **MPR** (Fig. 2f). Considering the **MLR9** readout, the nines complementary impulses of the amount standing in the related receiving device flow through it and via a group of lines generally designated **345** (Figs. 2b and 2a), through the **ML20—22** contacts to the **313ML9** accumulator magnets and back to ground. By such nines complementary impulses the **ML9** receiving device is brought to an all **9** position. The closure of contacts **ML23** allows a circuit to be established to the carry impulse line **324**, the circuit being completed through the now closed carry relay contacts **AV28** to the units order **313ML9** accumulator magnet. This provides for an entry of one in the units order of this accumulator and thereafter the regular electric transfer contacts provide for carries into higher orders. This resets the **ML9** receiving device to zero. The other multiple receiving devices are reset in a generally similar manner and individual reset circuits need not be traced therefor.

Referring now to Fig. 2f the nines complementary impulses flow through one section of **MPR** and up via lines **346** (see also Fig. 2e). From these lines the impulses flow through the now shifted **MP1—2** contacts, through the **313MP** accumulator magnets, to ground. This brings the **MP** receiving device to the all **9** position. A circuit is established from the carry impulse circuit **324**, through the **MP3** contacts now closed, through the carry relay contacts **AV11** now closed, back to the units order **313MP** accumulator magnet. The usual transfer circuit also energizes the higher order accumulator magnet. This brings the **MP** accumulator to an all zero condition.

17. RD to LQ transfer

At the end of the computation the amount standing in the **RD** accumulator is transferred into the **LQ** accumulator to set up the final result in **LQ**. Transfer of such amount is brought about

in the following manner: Referring first to Fig. 2g, a circuit is completed from line **301**, via wire **347**, through contacts **DD5** and **RD2**, all in the position shown, to add emitter **348**. From the add emitter impulses are emitted to **RDR** and the impulses flow out through the **CA1—3** contacts now in shifted position to the **313LQ** accumulator magnets. In this manner the amount which previously stood in **RD** is transferred over and entered into **LQ**.

Before the foregoing operation is completed, provision should be made to terminate the computing initiating control, viz. to deenergize relay coil **JJ** (Fig. 2d). Provision should also be made to restore the cycle controller stepping relay to its off-contact position and reset of the **RD** accumulator should be effected and punching operations should be initiated. Furthermore, a new card feed cycle should be initiated. Deenergization of the **JJ** relay is brought about in the following manner: Energization of the **321ML** relay coil (Fig. 2e) will have opened contacts **ML3** (Fig. 2d). With such contacts open and at a later time in the cycle, upon opening of contacts **CC18** the stick circuit to relay coil **JJ** will be broken, whereupon this relay will be deenergized. This will disable the computing initiating control circuits and allow the contacts controlled by relay **JJ** to return to the position shown in the circuit diagram.

18. Initiation of fourth card feed cycle

Relay contacts **ML24** (Fig. 2d) become closed upon energization of relay coil **321ML** to energize the **E** relay coil as explained in section 10 (Fig. 2d, left side) which latter is held energized by the **FC2** contacts for the initiation of the next card feed cycle. Relay coil **E**, upon energization, closes the **E2** contacts. An idle cycle follows the machine cycle in which the **ML** and other entry receiving devices are reset and sometime during this cycle the card feed rack of the punching machine returns to normal position to close the **P1** contacts. At this time the **P1**, **E2** and **JJ2** contacts in the impulsion circuit for the card feed clutch control magnet **304** are now closed and at the end of this cycle the **CC29** cam contacts close to close a circuit from the ground through **CC29**, through the **P1** contacts, through **E2** relay contacts, through **JJ2** contacts, stop key contacts **303** to the card feed clutch magnet **304**, through the **D1** contacts now in the position shown, to line **301**. Thus, after the idle cycle a new or fourth card feed cycle now ensues. At this time, this same impulse is not directed to the **XC** cam clutch magnet **312** due to the previous opening of the **EB5** relay contacts (Fig. 2d) in a manner subsequently to be explained.

To restore the cycle controller stepping relay to normal position, relay contacts **ML4** (Fig. 2f) are provided. Such contacts shift to a reverse position upon energization of relay coil **321ML** and upon closure of cam contacts **CC28**, a circuit is established through the **AK5** contacts and the now shifted **ML4** contacts to energize the release magnet **341SA** of the stepping relay. The stepping relay then assumes its off-contact position.

19. RD reset

During the fourth or reinitiated card feed cycle, reset of the **RD** accumulator is effected during the first machine cycle and is initiated by the circuit previously described in section 12 which, it will be recalled, is established from line **301**, through cam contacts **FC14** (Fig. 2e) now closed, through

the DA1 contacts now closed, through the AK19 contacts now in the position shown, through the now closed A14 relay contacts to the 321D reset coil.

20. Punching result of computation on detail card

Punching operations on a detail card are initiated in the early part of the RD reset cycle in the following manner. Referring to Figs. 2c and 2d, when cam contacts CC4 close, a circuit will be completed through the CC4 cam contacts, FB3 relay contacts, RD8 contacts, down through the closed AK23 contacts and Ru1 contacts (Fig. 2c) in the position shown, to pick up Wu. A branch circuit also extends through the closed AK21 contacts and Nu1 contacts in the position shown to pick up Vu. Closure of contacts RD8 contacts and cam contacts CC4 also establishes, through normally closed FB3 contacts, a circuit to relay coil A, energizing it. Upon energization of relay coil A, a stick circuit is established for A relay by relay contacts A1, the circuit being completed back to ground through contacts LQ9 which are now in the position shown. With relay contacts A13 closed a stick circuit back to ground is afforded through stick contacts Wu1 and Vu1 for relays Wu and Vu. (Fig. 2c.)

The punch interposer magnet circuits will now be traced. Referring to Fig. 2h, line 301 is connected to one side of the set of interposer magnets 353 and the circuit is completed through one of these magnets, through one of the A2-12 contacts now in shifted position, to and through LQR and for the first product punching position to an outgoing readout line 354, through one of the Vu2-8 contacts and one of the Wu2-8 contacts to one of the plug sockets 355, through a plug connection to one of the plug sockets 356 (Fig. 2d). In the punch the usual readout strip and brush commutator device establishes a circuit to the line 357. The circuit from wire 357 back to ground is completed through the usual punch escapement contacts 358, through the FB4 relay contacts now in the position shown, through the A1 contacts now closed, through LQ9 or CC19 to ground. The energization of selected ones of the coils 353 will cause closure of the punch interposer controlled contacts 359 and upon closure of 359 there will be an energization of the punch magnet 360. Punching now takes place for the first result punching position. The usual escapement occurs in the punch and for succeeding orders of LQR the punch circuits are established not via wire 354 (Fig. 2h), but through successive ones of the contacts Vu2-8 and Wu2-8 which are now closed.

In the customary way the punch controlled contacts P5 (Fig. 2d) become closed on the card reaching the beyond the last column position and closure of such contacts brings about energization of relay coil B. Energization of relay coil B closes relay contacts B1 and the circuit is completed to the usual eject magnet 361 in the punch. Upon eject of the card under the control of the eject magnet 361, the contacts P3 become closed in the usual way and punch rack trip magnet 318 becomes energized when cam contacts CC1 close.

21. Skipping second master card idly through punching machine

Referring to Fig. 7 it will be observed that the punching of the product on the first detail card which controlled multiplication may consume three machine cycles, the first two of which are during the fourth card feed cycle. During the

second machine cycle of the fourth card feed cycle a second master card is being fed into the card receiving tray of the punching machine, this second master card having been analyzed by the brushes 371 during the third card feed cycle. As will be later described during the analysis of the second master card, such card will be analyzed to determine the type of computation the following detail card is to control. This following detail card is fed during the second machine cycle of the fourth card feed cycle past the brushes 371 but no analysis is made because the detail cards have no computing selecting perforations.

As is well recognized, the master card is utilized only for selecting the type of computation and it is, therefore, idly fed to the punching machine and ejected therefrom to the receiving hopper of the same. In all respects it is fed to the punching machine in the same respect as the first master card, that is to say, it is fed to the card receiving tray of the punching machine and is then fed endwise in the punching machine to the first column position and since no punching is effected on the master card it is idly skipped through the punching machine and ejected into the receiving hopper of the punching machine. These operations have been described in detail for the first master card in section 10 and therefore will not be repeated. It should be observed that the endwise feed of the second master card and the skipping through the punching machine may occupy four machine cycles prior to the fifth card feed cycle, which is assumed herein. During the first of such cycles there is reset of the LQ accumulator and is performed by the circuit previously described and described in Section 7.

22. LQ reset and ML and MP reset

In general, upon the closure of the last column punch contacts P5, the B relay coil (Fig. 2d) is energized to close the B2 contacts, the D2 contacts having been previously closed as a result of the energization of the D relay coil by the closure of the card lever contacts 317 as previously described. The circuit for effecting LQ reset is through the cam contacts CC27 (Fig. 2e) through the AK2 contacts, through the B2 contacts now closed, the HH2 contacts, the D2 contacts to 321LQ reset coil. During LQ reset LQ9 contacts (Fig. 2d) open, thereby breaking the stick circuit for relay coil A, and coils Wu and Vu.

During the following cycle there is a reset of the ML and MP entry receiving devices, such being automatically performed by means of the circuit previously described in Section 9. However, in view of the previous reset of such receiving devices this is an idle operation of the machine.

23. Initiation of fifth card feed cycle

When the punching machine has been normalized, a fifth card feed cycle automatically ensues, this being occasioned by the closure of the P1 contacts and through circuits previously described in detail in Section 10 this will transmit an impulse to the card feed clutch control magnet 304 to initiate the fifth card feed cycle. However, concurrent with this card feed cycle there is an XC cycle due to the transmission at this time of the same impulse that energizes the 304 card feed clutch magnet to the 312XC clutch control magnet. The reason why the 312XC clutch control magnet is energized at this time is that the impulse directed to the card feed clutch magnet passes through the AE4 relay contacts, thence through the G2 relay contacts, then serially

through EC5, EB5 and EA4 relay contacts, all of which are now closed at this time, thence through the 312XC clutch control magnet.

It will be recalled that during the first card feed cycle upon the analysis of a master card which is to select the multiplying computation, the EA relay coil is energized and the latter is held energized by the FC19 cam contacts. Such contacts open during the first machine cycle of the second card feed cycle, enabling the EA4 relay contacts (Fig. 2d) to remain in closed position. Hence, the previous deenergization of the EA coil enables the impulse to be transmitted to the 312 clutch control magnet in the third card feed cycle, thereby effecting an XC cycle.

24. Master card selection of dividing mechanism

Reverting to operations performed in the third card feed cycle in which the entry was made from the first multiplying control detail card, at this time the second or following master card may be analyzed at the control station in the second machine cycle of the third card feed cycle. It will be assumed that the second master card is perforated at the "8" index point position of a control column which calls for a dividing operation and referring to Fig. 2h a circuit will be completed in the second machine cycle of the third card feed cycle from line 301, through the FC15 cam contacts, conductor plate 370, analyzing brush 371 in a column to sense the "8" index point position of the control column, GA1 relay contacts, to the emitter 512 which, when it makes at the time the "8" index point is analyzed by brush 371, causes an impulse to flow from plug hub 502 via the plug connection from plug hub 502 to plug hub 516 to grounded relay coil EB. Relay coil EB closes its stick contacts EB1 and the stick circuit extends back through the EB1 relay contacts, and through the cam controlled contacts FC19 which maintains the energization of the EB relay coil to the end of the third card feed cycle. Since cam contacts FC19 are closed at the "D" position, relay coil EB will remain energized all through the subsequent multiplying operation but will be deenergized when cam contacts FC19 open during the first machine cycle of the fourth card feed cycle.

The EB relay, therefore, maintains the EB2 relay contacts in the impulse circuit to the DA or dividing control relay in closed position and during the first machine cycle of the fourth card feed cycle FC20 cam contacts close to transmit an impulse through the EB2 relay contacts to the DA control relay. The latter closes its stick contacts DA1 and the stick circuit extends back through such contacts to a plug hub 518, the plug connection from the latter to the plug hub 519, thence through the normally closed ED1 relay contacts, back to line 301. Hence, the DA relay remains energized until the ED1 contacts open during the initial part of the sixth card feed cycle by a circuit to be subsequently described.

The DA relay closes its DA6 contacts which are in the impulse circuit for the AK or dividing relay and with the DA6 relay contacts closed during the first machine cycle of the fifth card feed cycle when cam contacts FC17 close, a circuit will be closed from line 301 through cam contacts FC17, through the FA4 relay contacts now closed, thence through the DA6 relay contacts now closed to the grounded AK dividing relay. Relay coil AK will close its stick contacts AK1, the stick circuit extending through cam contacts FC18 which continues the energization of the AK relay for the

remainder of the card feed cycle in which it is energized or the fifth card feed cycle. Since cam contacts FC18 close at the "D" position, the energization of the AK relay is maintained during the dividing operation effected in subsequent computing cycles.

In the first machine cycle of the fifth card feed cycle the "B" amount is entered from the second detail card. The "B" amount, or dividend 10 amount, will be entered via the shifted DA2-5 contacts (Fig. 2e) and wires designated 513 (Figs. 2e, 2f, 2g) to the 313RD accumulator magnets (Fig. 2g). The "A" amount, or divisor, is entered into ML1-2, 3-6, 5, 7 and 9 as before, through 15 the K1-8 contacts. Buildup of the multiples of the divisor amount then ensues in the normal manner.

25. LQ reset in dividing operation

20 With the second detail card fed to the punching machine as previously explained for the multiplying detail card and in the beyond the last column position in the punching machine, relay coil B (Fig. 2d) will be energized and with the new card in the receiving tray of the punch, relay coil D (Fig. 2d) will be energized because card lever contacts 317 will have become closed. With relay coils D and B thus energized, relay contacts D2 and B2 (Fig. 2e) will become closed and 25 with such contacts closed the 321LQ reset coil will be energized by a circuit from line 301, contacts CC3 (Fig. 2e), the now transferred AK2 contacts, contacts B2 now closed, normally closed HH2 contacts, D2 contacts now closed, to the 321LQ reset magnet. Reset of the LQ accumulator will then be brought about in the manner previously explained and such reset will initiate the dividing computing operation by causing as 30 described the energization of the computing initiating coil JJ (Fig. 2d).

26. Dividing operations

On dividing operations (see Fig. 10), the various ML devices are utilized to afford all nine digital multiples of the divisor. The dividend amount is introduced into the RD accumulator. The successive quotient digits as they are obtained are set up in LQ. The MP receiving device is not utilized on dividing. Likewise the SP receiving 45 device is not utilized on dividing. Generally, the method of division which is used involves the concurrent comparing of all of the available digital multiples of the divisor with a comparison portion of the dividend on the dividend receiving device. 50 By such comparison there is a determination of which is the largest multiple of the divisor which is less than or equal to the comparison portion of the dividend. Having made such determination there is a selection of the corresponding 55 quotient digit and such quotient digit is entered into the quotient receiving device LQ. Also the selected largest going multiple of the divisor is subtracted from the comparison portion of the dividend. Further operations then follow for another dividend comparison operation and so on 60 until the computation is complete.

It may be further explained that if none of the divisor multiples is contained in the comparison portion of the dividend which is being compared, there is a new comparison effected immediately 70 with a newly selected comparison portion of the dividend and that there are no idle cycles taken up either with unnecessary subtractions or for the introduction of a zero or zeros in the quotient 75 receiving device.

27. Elimination of shift of DD and DR entry in respective entry receiving devices

Referring to Fig. 10, it will be noted that the divisor 6 is not shifted to the left on entry into the ML receiving devices and that the dividend 92 is not shifted to the left on entry into the RD receiving device. Provision is made, however, to shift the wiring connections from the readouts of the ML and RD receiving devices in accordance with the number of zeros to the left, or in other words according to the denominational size of the amounts entered in these receiving devices.

Referring now to Fig. 7, it will be noted that in the first machine cycle following the fifth card feed cycle in which dividend and divisor entries were made from the second detail card into the ML and RD receiving devices, the MLR and RDR readouts are presensed for zeros to the left and accordingly controls are set up to route the entries from such readouts to the comparing units.

Referring to Fig. 1a, setup relay units N—R are provided, which in general construction, are similar to the electromechanical relay units fully disclosed in Patent No. 2,295,448 and shown in Fig. 17 therein. In the N—R unit, the tripping magnets are designated N (Fig. 2g) and R (Fig. 2b) with *u*, *t*, etc., suffixes indicating denominational order. It will be understood that magnets N and R are generally similar in function to the AD magnets of Fig. 17 in Patent No. 2,295,448.

It will be assumed that the machine is performing the division calculation of Fig. 10. Accordingly, in the first machine cycle following the fifth card feed cycle or the last machine cycle of the XC cycle, the MLR₁, 2 and RDR readouts are tested for the presence of zeros at the left. Referring to Fig. 2d when cam contacts XC₁₈ close, a circuit will be completed through the now closed AK₂₄ contacts to energize relay coil AF. The closure of relay contacts AF₁ and AF₂ (Fig. 2b) will complete a circuit from line 301, through contacts AF₁, to wire 600 connecting all zero spots, right hand brush T of the tens order of the MLR₁—2 readout, through the common segment, relay contacts AF₂, the Rt relay tripping magnet to ground. It will be observed, that if the brush U of the units order of the MLR₁—2 readout was also standing on zero, and a significant digit was in the hundreds order, by closure of contacts AF₃, the Ru magnet would also be energized. In much the same manner, and by an obvious circuit shown in Fig. 2g the closure of relay contacts AF₄ and AF₅—8 will complete circuits for the example assumed through the hundreds and thousands orders of RDR to energize tripping magnets N_h and N_{th} because such orders represent zeros.

It has been explained that, at the completion of the fifth card feed cycle with the second detail card in the receiving tray of the punch, an LQ reset is brought about. As the machine is now conditioned for dividing, relay coil LX (Fig. 2d) will be energized immediately after energization of 321LQ. Relay coil 321LQ closes contacts LQ₁₄ to close a circuit, from line 301, AK₂₇ contacts now closed, relay coil LX, LQ₁₄ contacts to ground. A stick circuit is provided for relay coil LX through the LX₁ stick contacts and cam contacts CC₃₉. Late in the same machine cycle the LQ reset occurs, a circuit will be completed from ground, through the AN₁₁ contacts now in the position shown (Fig. 2c) cam contacts CC₃₈, LX₂ contacts, now closed, AK₂₂ contacts, transferred Rt₁ contacts, Ru₁ contacts, relay coil Wu to line 301. A branch circuit also extends through the now closed AK₂₀ contacts, transferred N_{th1}

contacts, transferred N_{h1} contacts, N_{t1} contacts in the position shown, relay coil Vt, to line 301. Relay coils Vt and Wu have stick circuits provided through their associated stick contacts Vt₁ and Wu₁, the now closed AK₂₅ contacts and the LQ₉ contacts to ground. The same impulse used to energize the V and W coils is also used by an obvious branch circuit to energize the 321N—R coil which causes the N and R relay unit to be subsequently reset in the customary manner.

Summarizing for the example assumed, relay coils Vt and Wu are energized for a purpose made clearer later on.

Upon LQ reset the LQ₁₀ contacts (Fig. 2f) are closed. Inasmuch as the machine is set for dividing and contacts AK₂₈ are closed, current will be supplied through cam contacts CC₁₁, through AK₂₈, through LQ₁₀ to the divisor reset coils 321AZ in the comparing units, which are similar in function to 321AZ reset coils of Fig. 14 of Patent No. 2,295,448. This will release all of the divisor side sectors and allow them to be restored so as to be in position to receive a setting of the divisor multiples thereon.

28. Comparison of dividend with divisor multiples

The machine is now ready to compare the comparison portion of the dividend with all of the divisor multiples. In general, this is effected by reading out a comparison portion of the dividend from the RDR device, setting such portion of the dividend up on one side of all sections of the comparing units and at the same time reading out from the multiple readouts the various divisor multiples, each of which multiples becomes set up on one section on the other side of the comparing units. This operation will now be traced on the circuit diagram.

It will be recalled that during multiplying operations the comparing units CU were not in operation. In dividing computations, however, such units are placed in operation. This is effected by maintaining energized the clutch magnet 342 (Figs. 1a and 2d right side). The circuit for energizing clutch magnet 342 is completed from line 301 through the closed AK₂₇ contacts, through 342 and to ground. The maintained energization of 342 releases a one-revolution clutch to place the drive shafts 94 and 97 of the CU units (Fig. 1a) in timed operation with shaft 50.

A comparing cycle is initiated by the energization of relay coil LL (Fig. 2f) which becomes energized in the following manner: As previously explained, the computing initiating relay JJ was energized upon LQ reset. Energization of such relay closes contacts JJ₄ (Fig. 2f). A circuit is completed from line 301 (Fig. 2f) through the now shifted AK₅ contacts, through the CC₉ contacts, and through all of the 9Cu₁, 8Cu₁, etc., transfer contacts now in the position shown and finally through the 1Cu₁ contacts, through the JJ₄ contacts now closed, through the LL relay coil and back to ground. LL once energized is provided with a stick circuit extending back to line 301 through stick contacts LL₁ and cam contacts CC₁₃. After the foregoing stick circuit is established, cam contacts CC₁₄ close and establish a circuit through the non-shifted H₄ contacts to energize magnet 340SB of the SB stepping switch. With magnet 340SB energized the switch arms SB of this relay (Fig. 2f, top) are stepped to the first contact position.

Shortly after the switch arms of the stepping relay have advanced to this position, a circuit is

completed from line 301, through the H5 contacts now closed, through cam contacts CC8, through the switcharm of the stepping relay, through the CSa column shift relay coil and back to ground. Another circuit is established through the CC11 contacts, through the LL2 contacts now closed, through the stepping relay switch arm, through the BB relay coil and back to ground. A branch circuit is also established to energize relay coil DD. With coils BB and DD energized, they are maintained energized by their respective stick contacts BB1 and DD1, the stick circuit extending back to line through cam contacts CC10.

It may be explained that column shift relay CSa and relay coil DD cooperate to control the readout of the dividend comparison portion from RDR and contacts BB are utilized to control the readout of the various divisor multiples from the MLR readout devices.

The manner in which a comparison portion of the dividend is set up on the comparing units will now be described. It will be understood that the comparison portion of the dividend includes a selected number of columns. The number of columns selected is determined by the CSa relay. Referring to Fig. 2c, a circuit is completed from line 301, via wire 347 (see also Fig. 2g) to and through the now shifted DD5 contacts, to an add emitter 348. With such emitter in circuit, impulses are emitted through RDR, via a set of lines 385, through the now shifted DD6-9 contacts, through the now closed Vt9-12 contacts, through the now closed CSa1-2 contacts, through the shifted DD2-4 contacts, via lines 387 (see also Fig. 2c) and to the dividend side comparing magnets generally designated 1AW, 2AW, etc. which are the same as the similarly designated magnets of Patent No. 2,295,448.

It will be understood that the comparison portion of the dividend is set up in multiple in the comparing units, that is to say, there are nine identical setups, of the comparison portion of the dividend in order that there can be comparing between each setup and nine different divisor multiples. In the typical problem under consideration, the comparison portion of the dividend which was so set up is the amount of 92 (see Fig. 10). The setup of the multiples of the divisor on the other side of the comparing unit sections will now be described.

It has been previously explained how relay coil BB (Fig. 2f) becomes energized. With such relay coil energized all of the contacts BB2-28 (Fig. 2b) become closed. Add emitter 314 will be placed in circuit in the following manner: From line 301 to the non-shifted MM1 contacts and ML2 contacts to the add emitter 314. Such add emitter will emit impulses to and through all of the MLR readout devices and the multiple amounts available on such readouts will be individually transmitted through the now closed BB2-28 contacts, and Wu9-26 contacts to the various divisor multiple comparing magnets 1AZ, 2AZ, 3AZ, etc. Note that the Wu9-26 contacts cause the shift of entry one place to the left. It will be understood that the divisor multiple side of the comparing units will receive settings of the different divisor multiples in the manner more fully explained in Patent No. 2,295,448. The comparing units operate in the manner explained in this patent to make suitable settings of the brushes upon comparing commutators.

Having entered both the divided comparison portion in a multiple manner into the comparing units and having entered the various multi-

ples of the divisor in the other side of such comparing units the brush devices of the comparing units receive their settings, in the manner previously explained, to indicate a greater than, an equal to or a less than condition. As shown in Fig. 2c, the comparing unit commutators are in sections, one section being provided for each multiple.

Referring to Fig. 2c top, it will be noted that the 10 comparing unit commutators are shown diagrammatically and as sectionalized, one for each multiple and elements 117, 122, 123 are the same as in Patent No. 2,295,448. For each section there is an associated relay coil such as 9CU for a 9 multiple, an 8CU for an 8 multiple and so on. The brush action of the comparing devices is adapted to prevent energization of all magnets relating to multiples which are higher than the comparison portion of the dividend and to permit energization of magnets related to multiples equal to or less than the comparison portion of the dividend.

With the problem of Fig. 10, the only magnet which will be energized is relay magnet 1CU. The circuit energizing this magnet is from line 301 (Fig. 2g), via wires 347 and 388 (see also Fig. 2c), through cam contacts CC12, relay contacts DD10 now closed, through the commutator associated with 1CU, through 1CU and back to ground. At this point it may be explained that if the 4 multiple was the selected multiple, the 4CU coil, the 3CU coil, the 2CU coil and the 1CU coil would be energized and all higher number magnets above 4CU would not be energized.

It may be explained that on a comparing cycle 35 which takes a single machine cycle the setup of the comparison portion of the dividend and of all the divisor multiples is made during the first portion of the comparing cycle. Immediately after the setup is made and in the same machine cycle 40 testing is effected. All testing is done concurrently for all multiples.

Referring now to Fig. 2f the energization of relay coil 1CU will have shifted relay contacts 1CU1 to reverse position from that shown and upon closure of CC9 current flows through contacts 1CU1, to and through the 1X multiple selecting relay and through the MM relay to ground. The multiple selecting relay 1X is maintained energized through stick contacts 1X1, the stick circuit extending back to line through CC15. It may be mentioned that this 1X relay coil is energized in one cycle just after the commutator test is made and that such relay is maintained energized through a portion of the next cycle to select the 1 multiple which is to be read out from the MLR1 device and which multiple is to be subtracted from the dividend comparison portion of the divisor. The 1X multiple selecting relay also selects a related quotient digit for entry into the quotient receiving device LQ. Relay coil MM is maintained energized as long as the 1X coil is maintained energized, being in circuit therewith.

Previously when subtractive entries were made 65 for resetting purposes the elusive 1 which was introduced into the accumulator to bring the all 9 setting of the accumulator wheels to a zero setting was introduced after the complementary entry. In subtracting the divisor multiple, however, the elusive 1 entry is made during a comparing cycle. In this connection it is to be noted that such elusive 1 is only introduced into the RD accumulator in the event that a multiple is to be subtractively introduced into such accumulator in the following cycle. If no such mul-

multiple is to be introduced the entry of such elusive 1 in the comparing cycle is suppressed.

At the carry time in the comparing cycle, the carry impulse flows from line 324 (Fig. 2g) through the now closed MM2 contacts, through the Vt13 contacts now closed, through the CSA5 contacts now in shifted position through the now closed AK34 contacts to and through the 313RD accumulator magnet in the units order. It may be explained that the order in which such entry is made is selected under control of coil CSA, in this instance, by the CSA5 contacts and the Vt13 contacts. Such carry impulse for subsequent steps of the computation will be introduced into other orders.

It has been explained that if there was no going multiple for any given comparison portion of the dividend that no elusive 1 entry would be made. Such entry is suppressed because of the fact that, in the event that no going multiple is found on test none of the X magnets will be energized because none of the O-CU, 1CU to 9CU relays will be energized. With no X coil energized there will be no energization of coil MM and accordingly with MM deenergized the MM2 contacts will remain open and no elusive 1 entry can be effected. On a comparing cycle with a relay coil such as 1CU energized, the energizing circuit to coil LL (Fig. 2f) will be interrupted, since a shift of contacts 1CU1 cuts off the circuit.

Unless LL is energized it is impossible to energize the stepping switch magnet SB. All of the SB switch arms remain on their first contact position and inasmuch as contacts LL2 are open, even though cam contacts CC11 close, there will be no energization of either BB or DD. However, relay coil CSA will be energized again under the control of CC8 on the next machine cycle following the above described comparing cycle. Accordingly, the CSA1-2 contacts (Fig. 2g) will be again closed on the following machine cycle after the comparing cycle. In such cycle, the relay MM is maintained energized as explained before. Accordingly, relay contacts MM1 (Fig. 2b) will shift to reverse position from that shown and a circuit will be established from line through the MM1 contacts in shifted position to the subtract emitter 344.

Such emitter will emit nines complementary impulses through the MLR1 readout only. Impulses flow out of this readout, through the 1X2-4 contacts which are maintained closed by the energization of 1X during this cycle. Nines complementary impulses representative of the nines complement of 60, i. e. 39, flow over the lines 333 (Figs. 2b, 2f and 2g), through the now shifted AK39-41 contacts through the Wu27-29 contacts through the contacts DD2-4, in the position shown, over the lines 386, through the now closed CSA1-2 contacts, through the Vt9-12 contacts, non-shifted DD6-9 contacts and into the proper columnar orders of the RD accumulator, energizing the proper ones of the 313RD magnets. This operation will deduct the amount of 60 from the amount of 92, the comparison portion of the dividend in this accumulator (see Fig. 10). It will be recalled that the elusive 1 entry into this accumulator has been previously made and that the regular transfer mechanism of the accumulator will provide for transfer to higher order when required.

29. Entry of quotient digit

With the multiple selecting relay coil 1X energized a supplemental contact 1X5 (Fig. 2g)

will be closed. The DD5 and the RD2 contacts are now in the position shown and accordingly add emitter 348 is in circuit. A "1" impulse is emitted through the 1 bus of RDR, through the now closed 1X5 contact, through the AK35 and CSA1 contacts now closed, to the left hand accumulator magnet of LQ. This will enter the quotient digit of 1 in such accumulator.

On the quotient entering and subtracting cycle, 10 inasmuch as the DD relay coil was not energized, contacts DD10 (Fig. 2c) are in open position. Accordingly, even if CC12 contacts close there will be no energization of any of the CU relays. Accordingly, with none of such coils energized 15 the O-CU1, the 1CU1, etc. contacts of Fig. 2f remain in the position shown and upon closure of CC9 current supply is afforded through the J4 contacts to energize relay coil LL. Relay coil LL when energized will close its stick contacts 20 as before described and there will be another energization of stepping relay coil 340SB under the control of contacts CC14. Accordingly, switch arms of SB will step to the secnd contact position. After comparison is made with one dividend comparison portion at the time the multiple selecting relays are energized under control of contacts CC9, a supplemental circuit is established through coils 321AW to ground. These coils are the reset coils of the comparing unit 30 pertaining to the comparison portion of the dividend (see Fig. 14 of Patent No. 2,295,448). With such coils energized the dividend comparison side of the comparing units becomes restored so that a new dividend comparison portion can be introduced therein. It will be understood that the divisor multiple side of the comparing unit retains the divisor multiples during all deducting and quotient entering operations.

Referring to Fig. 10, the RD accumulator in 40 effect now has standing in it the remainder amount of 3200. There is now to be another comparison operation and with such comparison operation there is a different comparison portion of the dividend which is selected for comparison. 45 In Fig. 10 it will be noted that the first comparison which has been previously described pertains to the two extreme left hand orders of the dividend and the second comparison pertains to the next three orders. There must, accordingly, 50 be a column shift to take a different comparison portion of the dividend from the RD receiving device.

It has been previously explained how the SB stepping switch was brought to the second contact position. It was also explained that the relay coil LL was energized. With relay coil LL energized relay contacts LL2 (Fig. 2f) are closed and accordingly upon closure of cam contacts CC11 a circuit is completed through a switch arm 60 of the stepping switch to energize relay coil DD. It will be noted that there is no energization of relay coil BB because the second contact of the stepping switch and those thereafter are not wired in circuit to relay coil BB. Accordingly, at 65 this time there is no energization of relay coil BB. With relay coil DD energized, it is maintained energized in the customary manner and following its energization cam contacts CC8 close and a circuit is established to energize column shift coil CSb. It will be noted that relay coil CSA is not now energized since the switch arm of the stepping switch is in the second contact position and out of circuit with CSA. With the coil CSb 70 and relay coil DD energized, their associated con-

tacts shift to a reverse position from that shown in the circuit diagram.

Referring to Fig. 2g with coil CSb energized, contacts CSb1-3 close and there is a new readout relation established with RDR. The readout relation is now such that the three left hand columns of the dividend amount are selected for readout and entry into the dividend side of the comparing units. The entry circuit will now be traced. From line 347 (Figs. 2c and 2g), through the DD5 contacts now shifted, to the add emitter 348, from the add emitter impulses are emitted through RDR, to lines 385, thence through the DD6-9, Vt9-12 and AK10-12 contacts now shifted, through the closed CSb1-3 contacts, through the shifted AK7-9 contacts, lines 386, thence through the now shifted DD2-4 contacts, to lines 387, thence to Fig. 2c and to the various 1AW, 2AW, etc. comparing unit magnets. This operation will have set up the new comparison portion of the dividend, viz. 320 in the various comparing units.

It will be recalled that the divisor multiples still remain set up in the divisor side of the comparison units. There is then a further comparison effected and the comparison commutators and circuits of the comparing unit bring about an energization of all of the CU coils from 1CU up to and including 5CU but leaves coils 6CU, 7CU, 8CU and 9CU deenergized. With the 5CU comparison relay coil energized, the related relay coil 5X (Fig. 2f) becomes energized under the control of CC9, over the circuit previously described, but which in this instance, is completed through the now shifted 5CU1 contacts to the multiple selecting relay 5X. When relay coil 5X is energized, relay coil MM likewise becomes energized in the manner previously explained. Both 5X and MM are held energized through the 5X1 stick contacts.

In the comparing cycle and at the carry time in such cycle, provision is made for introducing an elusive 1 into the RD accumulator in extreme left hand order. Such elusive 1 entry is made generally in the manner previously explained except that at this time the CSb4-7 (Fig. 2g) contacts are in shifted position due to the energization of CSb. With relay coil MM energized, the MM2 contacts are closed and a circuit is completed from line 324 at the carry time, through MM2, through the now closed Vt13 contacts, through the now shifted CSb6 contacts through the AK31 contacts down to and through the thousandths order 313RD accumulator magnet. This will enter the elusive 1 in such order. It will be noted that the Vt14 contacts are closed to provide a carry from the thousandths to the units order of the RD accumulator. This circuit is from line 324, relay contacts AV5, contacts Vt14, relay contacts AK34, to the units order 313RD to add the elusive unit in such order. On the following cycle the 5 divisor multiple is entered subtractively into the RD accumulator and the 5 quotient digit is entered into the proper columnar order of LQ.

Referring to Fig. 2b energization of the 5X multiple selecting relay coil, brought about as previously explained, will close the 5X2-4 contacts. The energization of relay coil MM will shift MM1 contacts to reverse position and place the nines complementary emitter 344 in circuit with line 301. Nines complementary impulses flow from the 344 emitter, through the MLR5 readout, out through the 5X2-4 contacts to the lines 333 through the transferred AK39-41 contacts, now

closed, Wu27-29 contacts (see also Figs. 2f and 2g), through the non-shifted DD2-4 contacts (DD having now become deenergized), through the shifted AK7-9 contacts, through the closed CSb1-3 contacts, CSb having been reenergized in such cycle since the stepping relay SB remains on the two contact position, through the AK10-12 contacts now shifted, through the DD6-9 contacts in the position shown, to the accumulator magnets of the RD accumulator. This will enter the nines complement of the 5 multiple of the divisor into such accumulator. Concurrently with the foregoing deducting operation the 5 quotient digit is entered into LQ. The energization of relay coil 5X will have closed contacts 5X5 (Fig. 2g). Add emitter 348 will now be in a circuit which extends through the DD5, and the RD2 contacts in the position shown. A current impulse will be emitted from the 5 spot of the add emitter 348 to and through the RDR readout and through the closed 5X5 contacts, through the AK36 contacts, the CSb8 contacts, down to the hundreds order of accumulator magnet of the LQ accumulator. This will enter the 5 quotient digit in such order of this accumulator.

Referring to Fig. 10, in the computation illustrated, the quotient is carried to two places. It will be assumed in this description that it is desired to divide only to this number of places, and computing is now terminated in a manner now to be described.

30. Place limiting device

Referring to Fig. 2f and Fig. 8 the insertible plugboard will have provided a plug connection from socket 389 to the second socket 390 from the left. The second socket from the left is plugged up because the computation is to be carried to two quotient places. If the computation was to be carried to further quotient places, the third or fourth socket 390 from the left would be plugged up. During the second multiple deducting cycle just described, relay coil DD will be deenergized and accordingly the DD10 contacts (Fig. 2c) remain in open position. There will accordingly be no energization of any of the CU relay coils. With none of such relay coils energized the 1CU1 to 9CU1 contacts (Fig. 2f) will remain in the position shown so that upon closure of cam contacts CC9, relay coil LL will become energized. With such relay coil LL energized the relay contacts LL3 will be closed and upon closure of CC17 the circuit will be completed through LL3, through the switch arm of the stepping switch now still in the second contact position, through the plug connection from socket 390 to socket 389 to energize relay coil H. H being energized, closes its stick contacts H1 and the stick circuit is completed back to line 301 through ML5 contacts now in normal position. The energization of relay coil H will have shifted relay contacts H4 (Fig. 2f) to a reverse position from that shown at a time prior to the closure of cam contacts CC14. Accordingly, with such CC14 contacts closed, a circuit is completed through the stick contacts of LL1 of LL, through the CC14 contacts, to the release magnet 341SB of the stepping switch. With this operation, due to the shift of contacts H4, the stepping switch magnet 340SB will be out of circuit. Energization of the 341SB release magnet will release the stepping switch and allow it to return to normal home position, i. e. the position shown in the circuit diagram. It may be mentioned that no circuits are inadvert-

ently established by the switch arms on SB on restoration because on restoration the H5 relay contacts are in open position. The foregoing restoration of the stepping switch and opening of contacts H5 terminates further energization of the CS magnets, the BB or the DD magnets.

31. Reset of ML and RD accumulators

The machine has now reached the stage in its operation in which it is ready to record the quotient upon the detail card beginning in the cycle the various ML multiple receiving accumulators and the RD device are reset. Reset of the ML devices is brought about in the following manner: Energization of relay coil H (Fig. 2f) in the manner previously explained will have caused closure of relay contacts H3 (Fig. 2e). Upon closure of CC3, a circuit is established from line 301, through the AK2 contacts now in shifted position, through contacts H3 and AK16 now closed, through 321ML, to ground. A branch circuit is also completed through the AK19 contacts now shifted, through relay contacts A14, through the 321RD reset relay coil and back to ground. Energization of 321ML and the 321RD reset coils will bring about electric reset of the corresponding accumulators. The detailed impulse circuits for resetting will not be traced as these have been previously traced. The energization of the 321ML relay coil also serves to deenergize the computing initiating relay coil JJ as follows: Opening of relay contacts ML3 (Fig. 2d) breaks the stick circuit for coil JJ but the time of deenergization of coil JJ is timed by the CC18 cam contacts following the opening of relay contacts ML3.

The energization of relay coil 321RD brought about as just explained causes the closure of contacts RD8 (Fig. 2d). Upon closure of cam contacts CC4, the circuit is established through the now closed FB3 and RD8 contacts, through the A relay coil to line 301, and a stick circuit is provided back to ground through the A1 and LQ9 contacts.

32. Recording of quotient on detail card

Referring to Fig. 2h, it will be noted that there is a column shifting arrangement similar to Patent No. 2,295,448 intermediate plug sockets 355, which are sockets which are connected to the punch readout strip sockets 356 (Fig. 2d), and LQR (Fig. 2h). Such column shifting arrangement is provided by the multicontacts controlled by the various V relays and the W relays. The W relays are selectively energized according to the number of zeros to the left in the divisor and the V relay coils are selectively energized according to the number of zeros to the left in the dividend. With relay coils Vt and Wu energized, there will be a closure of the related contacts Vt2-8 and Wu2-8 and the closure of these contacts in combination will establish a readout relation between LQR and the sockets 355 so that there will be a punching not in the extreme left hand field of the record card, but in a field shifted two columns to the right from the extreme left hand field.

It will be assumed that all of the seven sockets labeled 355 (Fig. 2h bottom) are connected to sockets 356 (Fig. 2d). If the circuits from the two left hand sockets of the 355 group and the extreme right hand 355 sockets are traced it will be found that their circuit extends back to a line 391, which line connects to a line 392 and that this circuit is completed back to line 301, through the now closed A2 and A3 contacts to and through

the zero interposer magnet 353. This will provide for punching zeros on the record card in columns of the quotient field not controlled by LQR.

Now referring to the third socket from the left of the 355 group, it will be noted that this circuit is completed through the Wu4 contacts, through the Vt5 contacts, to a line which extends up to the thousands order of LQR. Inasmuch as the brush in this order is standing upon 1, the one punch selecting interposer magnet 353 will be energized during the punching operation. If the line from the fourth socket from the left of the 355 sockets be traced, it will be noted that this circuit is completed through the Wu5 contacts, through the Vt6 contacts, to the hundreds order of LQR. In this order, the brush is standing on the 5 spot so that the line will be completed through A8 contact to and through the five interposer magnets 353.

Referring now to the two sockets 355, which are in the second and third columns from the right of the group, it will be noted that circuits are completed through Wu6-1 and Vt7-8 to the tens and units orders of LQR. The brushes in these orders stand at zero, therefore there will be a circuit completed from both orders back to the zero interposer punch selecting magnet 353.

The foregoing description has explained the circuits for selectively reading out amounts to the punch on final recording. Punching occurs successively column by column in the usual way, the control circuits being those traced in detail for result recording on multiplying, but it may be mentioned that the return circuit from any plug socket 356 is via the punch readout brush to the common strip of the readout, thence via wire 357 (Fig. 2d), through the usual escapement contacts 358 of the punch, through FB4 relay contacts in the position shown, through the stick contacts A1 and LQ9 thence back to ground. The energization of any interposer magnets 353 (Fig. 2h) causes the closure of the interposer controlled punch magnet contacts 359 in a well known way (Fig. 2d) and energizes the punch magnet 360 in the usual manner. Punching then proceeds in the usual way column by column and eventually the card reaches the beyond last column position and closes P5 contacts energizing coil B. Energization of B closes contacts B1 and energizes the eject magnet 361 of the punch. Card ejection then occurs and contacts P3 become closed to condition control circuits for a succeeding computation.

33. Initiation of sixth card feed cycle

Following the dividing operation the sixth card feed cycle automatically ensues and is effected immediately following the ML and RD reset cycle. Such card feeding operation is initiated in the following manner and it should be observed that it causes the feeding of the third master card into the punch tray and concurrently feeds the following detail card past the analyzing brushes 371 but the analysis thereof is ineffective.

Relay contacts ML24 become closed upon energization of relay coil 321ML to energize the E relay coil (Fig. 2d, left side) which is held energized by the FC2 contacts for the initiation of the next card feed cycle. Relay coil E closes the E2 contacts and during the ML reset cycle the card feed rack of the punching machine returns to normal position to close the P1 contacts. At the end of the ML reset cycle, CC29 cam contacts close to close a circuit from ground to

CC29, through E2 relay contacts through the JJ2 contacts, stop key contacts 303 to the card feed clutch magnet 304, through the D1 contacts to line 301. This will initiate the sixth card feed cycle.

At this time, the impulse directed to the card feed clutch magnet 304 is not directed to the XC cam clutch magnet 312, due to the previous opening of the EC5 relay contacts (Fig. 2d) in a manner to be subsequently explained.

During the sixth card feed cycle cam contacts FC22 (Fig. 2h) close at the initial part of the cycle and close a circuit from line 301 through cam contacts FC22 (Fig. 2h), through the EC4 relay contacts now closed, to the ED relay. The ED relay opens the ED1 contacts, thereby breaking a stick circuit for the previously energized dividing control relay DA, bringing it to a de-energized status. Thereafter, cam contacts FC19 open to deenergize the EC relay. Of course, the AK relay having been held energized by the FC18 contacts deenergizes when the latter open and shortly after the beginning of the sixth card feed cycle, all of the control relays involved in the dividing selecting operation are restored to normal position.

From Fig. 7 it will be observed that the operation of the punching machine to punch the quotient on the detail card which was utilized to control the dividing operation is initiated in the cycle in which the ML receiving devices and RD accumulator are reset. Such quotient result punching operations are also carried out during the sixth card feed cycle and during the second machine cycle thereof the third master card will be fed into the punch tray, which operation is precisely the same as that explained for the first master card. Concurrently therewith the detail card which follows the third master card is fed past the brushes 371 for ineffective analysis of the data thereon.

34. Feeding third master card idly through punching machine

Following the sixth card feed cycle, four machine cycles ensue, during which time disposition of the third master card is made in the respect that after having been fed onto the punch tray it is fed endwise in the punching machine to the first column punching position and then idly 45 skipped through the punching machine and ejected from the card carriage thereof after which time the feed rack returns to initial position so as to cause the initiation of the seventh card feed cycle. These four machine cycles correspond in function and operation to the four machine cycles following the fourth card feed cycle in which identical operations are effected for the first and second master cards. It is thought, therefore, unnecessary to repeat the description of such operations at this time.

35. Reset of LQ, ML, MP accumulators

Also, during the first machine cycle following the sixth card feed cycle there is a reset of the LQ accumulator effected by circuits previously described in detail in Section 7. The reset of the ML and MP receiving devices also takes place during the second machine cycle of these four machine cycles following the sixth card feed cycle 65 and is accomplished by the circuit previously described in Section 9.

36. Initiation of seventh card feed cycle

Upon termination of these four cycles provided 75

to pass the master card through the punching machine and the resetting of the LQ, ML and MP accumulators, the card feed rack returns so as to close the PI contacts (Fig. 2d), whereupon an impulse is directed to the card feed clutch magnet 304 to initiate the seventh card feed cycle but at this time the impulse will also be directed to the XC clutch magnet 312 because EA4, EB5 and EC5 relay contacts are closed so as to cause an XC cam cycle. It will be assumed now that the third master card passing through the machine is to effect an

$$\frac{A \times B}{C}$$

15 computation and the manner in which the selection of this computing mechanism is effected in the third master card feed cycle will now be described.

20 36a. Master card selection for conditioning the machine to effect $\frac{A \times B}{C}$ computation

25 Reverting to operations performed in the fifth card feed cycle in which the entry was made from the second detail card controlling the dividing computation, at this time the third or following master card may be analyzed at the control station in the second machine cycle of the fifth card feeding cycle. It will be assumed that the third master card is perforated at the "7" index point position of a control column which calls for an

$$\frac{A \times B}{C}$$

35 computation and referring to Fig. 2h a circuit will be completed in the second machine cycle of the fifth card feed cycle from line 301, through FC15 cam contacts, conductor plate 370, analyzing brush 371 in a column to sense the "7" index point position of the control column, GA1 relay contacts, to the emitter 512 which, when it makes at the time the "8" index point position is analyzed by brush 371, causes an impulse to flow from plug hub 521 via the plug connection from plug hub 521 to plug hub 517 to grounded relay coil EC. Relay coil EC closes its stick contacts EC1 and the stick circuit extends back through the EC1 relay contacts and through the cam controlled contacts FC19 which maintains the energization of the EC relay coil to the end of the fifth card feed cycle. Since cam contacts FC19 are closed at the "D" position, relay coil EC will be closed all through the subsequent multiplying operation but will be deenergized when cam contacts FC19 open during the first machine cycle of the sixth card feed cycle.

50 The EC relay, therefore, maintains the EC2 contacts in the impulse circuit to the DB or

$$\frac{A \times B}{C}$$

control relay in closed position and during the first machine cycle of the sixth card feed cycle, FC20 cam contacts close to transmit an impulse through the EC2 relay contacts to the DB control relay and through EC3 to energize the FA relay. The latter closes its stick contacts FA1, the stick circuit extending back through punch contact P2a to line 301. DB relay closes DB1 contacts and the stick circuit extends back through such contacts to a plug hub 518, the plug connection from the latter to the plug hub 519, thence through the normally closed ED1 relay contacts back to line 301. Hence, the DB relay remains

energized until the ED1 contacts open during the initial part to the card feed cycle following the termination of the

$$\frac{A \times B}{C}$$

5

computation. The FA relay remains energized until punch contacts P2a open.

The DB relay closes its DB2 relay contacts which are in the impulse circuit for the AN or 10

$$\frac{A \times B}{C}$$

15

computation relay and with the DB2 contacts closed during the first machine cycle of the seventh card feed cycle, when cam contacts FC17 close a circuit will be closed from line 301, through cam contacts FC17, through the FA4 relay contacts now closed, thence through the DB2 relay contacts now closed to the grounded AN relay. Relay AN will close its contacts AN1, the stick circuit extending through such relay contacts and cam contacts FC18 which continues the energization of the AK relay for the remainder of the card feed cycle in which it is energized for the seventh card feed cycle. Since cam contacts FC18 close at the "D" position, the energization of the AN relay is maintained during the

$$\frac{A \times B}{C}$$

20

computation and until the next card feed cycle following the termination of this computation.

A brush connected to the grounded GA relay (Fig. 2h) is separated from contact roll 370 by an intact portion of each master and detail card to retain the GA relay deenergized. However, in the sixth cycle when the third detail card, which is assumed to be the last detail card controlling the machine, passes by this brush as it is fed past the station comprising sensing brush 371, the GA relay will be energized to open contacts GA1. This prevents the emitter 512 from sending impulses to either EA, EB or EC relays during any subsequent card feed cycle, such as the seventh card feed cycle when cam contacts FC15 close. This takes care of improper operations on a last card condition of the machine.

During the fifth card feed cycle, the "C" or divisor amount will be analyzed by the brushes 308 for the "C" field and entered by plug connections between the related plug sockets 309 to sockets 500 (Figs. 2c and 8) and by wires 514 (Figs. 2a, 2b and 2c) the entry is directed through the closed DB3-4 contacts (Fig. 2c) to the 313SP accumulator magnets and stored in the SP accumulator. (See also Fig. 11). The multiplicand or "A" amount will be entered into the ML accumulators and the "B" or multiplier amount will be entered into the MP receiving device in the same way as described for the multiplying computation, and as outlined in Fig. 11.

Multiples of the "A" or multiplicand amount are built up in the same way as described for multiplying computations, as outlined in Fig. 7.

With relay contacts B2 and D2 closed (Fig. 2e), by circuits previously described in Section 7 for the multiplying computation an impulse is directed to 321LQ when cam contacts CC27 close, thus resetting LQ in the last machine cycle of the seventh card feed cycle.

37. $\frac{A \times B}{C}$ computation

Computing cycles for multiplication are initiated by the LQ reset, it being recalled that the circuit to energize JJ (Fig. 2d) is closed by LQ8 contacts. Also, closure of JJ5 contacts (Fig. 2f) initiate the transmission of an impulse to 340SA stepping switch magnet and thus the SA switch arms are stepped to their first contact position.

Since the same factors are involved in the

$$\frac{A \times B}{C}$$

computation as in the previously described multiplying computation relay coils ADu and ADt are energized, and also as described for the multiplying computation column shift coils CSb and CSc are energized.

Of course, with the same multiplier amount 27, MPR will represent 27 by the brush positions, thus selecting the 2 and 7 multiplicand multiplies for entry in the LQ and RD accumulators, with a subsequent transfer to RD from LQ so that the latter represents the final product, which is utilized as a dividend for the subsequent multiplying computation. These operations need not be redescribed at this time as they were previously described in detail for the same multiplying computation.

In the description of the multiplying computation the circuits to pick up H and KK were described and such relays are also energized in this computation to close contacts H3 and KK2 (Fig. 2e) to energize 321CY, 321MP and 321ML, effecting the reset of such units. However, differing from the previous description since contacts AN4 are now open (Fig. 2e) relay coil CA will not be energized. An impulse is also directed to 341SA resulting from the closure of ML4 contacts (Fig. 2f) and the SA switch arms restore to normal, as for the multiplying computation.

It should be noted that upon the completion of multiplication there is an automatic shift from multiplying to division, and while previously this was performed under master card control automatically closed circuits institute this change in computation.

In the cycle that MP is reset with MP5 contacts now closed (Fig. 2d), a circuit is completed from line 301, through AE relay coil, cam contacts CC30, MP5 relay contacts, relay contacts AN5 now closed, to ground. A stick circuit for AE relay is provided by stick relay contacts AE1 and cam contacts CC31. Before the end of the cycle in which AE was picked up and held energized, cam contacts CC33 (Fig. 2h) close, thus completing a circuit from line 301, cam contacts CC33, relay contacts AE3 now closed, relay coil AK to ground. This is the relay coil that changes the circuits to a dividing status. Relay coil AK closes its contacts AK1, and a stick circuit is provided by FC18 contacts which are now at rest and closed, to thus maintain relay coil AK energized until the next card feed cycle ensues.

The opening of relay contacts AE2 (Fig. 2d) opens the impulsive circuit for relay E, which it will be recalled, is the relay which initiates card feed by closing its contacts E2 to energize the card feed clutch magnet 304. Thus, while dividing operations are initiated, card feed is suppressed.

A different circuit from that described is effective to energize the magnet 304 to cause the rotation of the XC cams. This circuit is from line 301, clutch magnet 312, EA4, EB5, EC5 contacts 75 now closed, G2 contacts closed by the circuit pre-

viously described, AE4 contacts now transferred, AK4 contacts now transferred, cam contacts CC32 to ground. Contacts AE5 are shunted across G2 contacts to take care of the last card condition and in the place of the circuit being closed by G2 contacts it is closed by AE5 contacts. With AE4 contacts transferred the impulse cannot be sent to magnet 304 as before by this impulsive circuit.

The energization of the magnet 312 clutches the shaft which rotates the XC cams to the driving shaft so that an XC cycle follows as shown in Fig. 7 after conditioning the machine to a dividing status. During the first machine cycle of the ensuing XC cycle a circuit is closed to effect the energization of relay coil WW (Fig. 2d, left side) when XC1 cam contacts close by the following circuit: From the line 301 through relay coil WW, relay contacts AN6 now closed, AK18 relay contacts now closed, cam contacts XC1 to ground. Relay coil WW is energized during the entry part of the first machine cycle of the XC cycle so that the C amount is entered in the ML1-2, 3-6, 5, 7, 9 accumulators. This entry circuit is described as follows: From line 301, wire 347 (Fig. 2c), through SP2 contacts now in the position shown, through relay contacts WW3 now closed, to the emitter 410, thus connecting emitter 410 to the line 301. Additive impulses will now flow by the emitter 410 under control of the SPR readout and in accordance with the C amount standing on the SPR readout timed digital impulses will be transmitted through relay contacts SP3-4 now in the position shown and thence by wires 514 (Figs. 2c, 2b, 2a) the impulses will be directed to contacts WW1-2 which now are transferred and from such contacts, the impulses will pass through K1-8 contacts now closed and be directed to the ML1-2, 3-6, 5, 7 and 9 accumulators, thereby entering the C amount in such accumulators. With the C amount entered in such accumulators, a buildup of the multiples of the C amount is effected during the second and third machine cycles of the XC cycle precisely in the same manner as described for dividing operation. Hence, from the outline of the computation in Fig. 11, it will be observed that multiples of the C amount or -49 are represented in the ML receiving devices. The C amount is, of course, the divisor so that in the subsequent dividing operation all of the digital multiples of the divisor can be compared with the comparison portion of the dividend exactly as has been outlined in the description of the dividing computation.

Transfer of the amount in LQ to RD prior to the dividing operation is brought about in the following manner: Referring to Fig. 2d when cam contacts XC11 close during the entry part of the second machine cycle of the XC cycle, a circuit will be closed from line 301 through relay contacts AK21, relay coil AG, relay contacts AN8 now closed, cam contacts XC11 to ground. Referring to Fig. 2h the closure of AG1 relay contacts will connect the line 301 through LQ2 relay contacts, AG1 contacts now closed to the emitter 414. Impulses will be now directed by this emitter and under control of the LQR readout, impulses representative of the digital amount on LQR will be transmitted through LQ3-6 contacts now in the position shown through AG2-5 contacts now closed, through the 313RD accumulator magnets to ground.

During the third machine cycle of the XC cycle prior to dividing operations the LQ accumulator is reset in order that it may receive the subsequently derived quotient digits. Referring to

Fig. 2e when cam contacts CC3 close, a circuit will be closed from line 301 through cam contacts CC3, relay contacts AK2 now transferred, thence through cam contacts XC13 which are closed at the time cam contacts CC3 are closed, thence through relay contacts AK30 now closed, relay contacts AN9 now closed to the 321LQ reset coil, thereby causing the resetting of the LQ accumulator during the third machine cycle of the XC cycle as outlined in Fig. 7.

During this machine cycle there is a presensing of the amount standing in MLR and RDR to determine the presence of zeros and this is carried out by the circuits previously described in detail. With the dividend amount 0864 now represented in RDR, the zero testing circuit will sense the presence of a zero in the ten thousands order and accordingly relay coil Nth (Fig. 2g) will be energized. The transfer of the related contacts Nth (Fig. 2c) will accordingly cause relay coil Vh to be energized and its contacts Vh9-12 (Fig. 2g) will be closed to route the entries from RDR to the dividend side comparing magnets 1AW, 2AW, etc.

With regard to the divisor which is 049 (Fig. 11) it will be observed that there are no zeros in either the units or tens orders and accordingly none of the relays Ru or Rt (Fig. 2b) will be energized upon sensing MLR1-2 for zeros by the circuit previously described. Accordingly, with contacts Ru1 and Rt1 (Fig. 2c) in the position shown, relay coil Wt will be energized and the latter will shift its contacts Wt9-35 (Fig. 2c) to route the entries from all the MLR readout devices to the divisor multiple comparing magnets 1AZ, 2AZ, 3AZ. The above operations are effected just prior to dividing and for the reasons previously described in detail in connection with the dividing computation. The machine is now ready to divide the product of the previous multiplying computation by the C amount and dividing is carried out exactly in the manner previously described. During the first machine cycle after the XC cycle is terminated there is a comparison of the comparison portion of the dividend with the multiples of the divisor and in the next machine cycle the selected largest going multiple of the divisor is subtracted from the comparison portion of the dividend. In accordance with the selected largest going multiple, the corresponding quotient digit is entered in LQ. In the example outlined in Fig. 11, the first quotient digit is "1" and two subsequent machine cycles then ensue with repetitions of the dividing operations just described to secure the next quotient digit "7" which is also entered in the LQ accumulator. Obviously, with the machine set to secure two quotient digits by reason of the plug connections between 389 and 390 shown in Fig. 8, dividing operations will terminate when two quotient digits have been derived and thereafter quotient recording operations are brought about in precisely the same manner as has been described.

The final operations for this computation consist in resetting the ML receiving devices and the RD and SP accumulators. It will be recalled that for resetting the ML receiving devices a circuit is closed from line 301 to cam contacts CC3, AK2 contacts now transferred, through contacts H3 which are now closed because dividing operations have been terminated, through relay contacts AK16 to 321ML to ground. By a branch circuit an impulse is also directed through relay contacts AK19 now transferred, relay contacts A14 to 321RD reset coil. It will also be observed

65 66 67 68 69 70 71 72 73 74 75

that this impulse through AK17 now transferred is directed through AN10 contacts now closed, to 371SP reset coil. Accordingly, by these reset circuits the ML receiving devices and RD and SP accumulators are reset to zero.

As outlined in Fig. 7 this indicates the sequence of events when multiplying, dividing and a

$$\frac{A \times B}{C}$$

computation are effected in succession, determined by the passage of three master cards designated accordingly to select such computing mechanisms. It is obvious, of course, that further computing operations may then follow and such computing operations need not be in the same sequence as outlined in Fig. 7 and the type of computation may vary from master card to master card with repetitions of the same form of computation being accomplished under control of one or more detail cards, or changing from master card to master card.

Machine operations when a master card is followed by more than one detail card

In the previous description it was assumed that only one detail card preceded the master card which selected the dividing computation. However, this may not be the arrangement of cards and may change in the respect that more than one detail card follows each master card and upon such occurrence it is necessary that the machine continue with the same computation previously selected under control of the master card. By the following observations it will be evident that the machine will continue in the form of computation selected under control of more than one detail card, this now being explained in connection with multiplication as shown in the sequence diagram of Fig. 13.

This change would occur in the third card feed cycle wherein, instead of feeding the second master card in the second machine cycle of the third card feed cycle, a second detail card would be fed past the analyzing brushes 371 for ineffective analysis. Therefore, none of the control relays EA, EB or EC will be set up. The machine will accordingly, continue with multiplication after the multiplying operation for the first detail card.

During the fourth cycle none of the DA or DB relays will be picked up because it is assumed that a second detail card follows. Hence, the circuits at the beginning of the fourth card feed cycle are in the same condition as they are in the third card feed cycle and during the first machine cycle of this card feed cycle the second detail card is fed past the analyzing brushes 308. Multiplying operations then continue for the second detail card and the sequence of operations which take place are exactly as shown in Fig. 13 for a multiplying operation. If, in the fifth card feed cycle, a still following detail card is analyzed by the brushes 308, another multiplying operation will take place in the manner previously described and this will continue indefinitely until a new master card is analyzed by the brushes 371.

In the same manner after a master card has selected the dividing mechanism for operation and has been operated under control of the following detail card, a recomputation of division may follow for the next following detail card. In Fig. 7, it was assumed that in the fifth card feed cycle a division computation was initiated and in the event that a second detail card passes

through the machine it will be understood that like the sequence diagram in Fig. 13 the recomputation of division will be automatically effected after the sixth card feed cycle. Hence, with the sequence diagram of Fig. 7, the sequence of events in the sixth cycle will be changed to comprise those outlined in the fifth card feed cycle and machine operations will continue thereafter as shown for the cycles following the fifth card feed cycle. Hence, repetitions of division computations can be effected for as many detail cards as are passed through the machine after the initial computation for division.

It will be recalled, referring to Fig. 2h, that the stick circuit for the DA relay which selects the AK master computation relay and maintains the machine conditioned for dividing for one or more detail cards is held closed through the normally closed ED1 relay contacts. The ED relay remains unenergized until a master card is sensed which would select either the EA or EC relay when the machine is to be conditioned for multiplication or

$$\frac{A \times B}{C}$$

computation. Closing of the EA3 and the EC4 relay contacts energizes the ED relay which opens its ED1 contacts and now the previous computing condition of the machine will be changed, according to the particular master card designation sensed.

Also, the

$$\frac{A \times B}{C}$$

computation continues for more than one detail card until either the EA or EB relay is energized to condition the machine for multiplication or division. The computing condition of the machine is changed by the energization of the ED relay which breaks the holding circuit for the DB relay which is the relay that selects the AN relay or

$$\frac{A \times B}{C}$$

computation.

Accordingly, machine operations can be repeated for the

$$\frac{A \times B}{C}$$

computation as outlined in the sequence diagram of Fig. 7. The events which take place in the seventh card feed cycle and following machine cycles may be repeated for as many detail cards as pass through the machine after the first detail card which controls the computation

$$\frac{A \times B}{C}$$

Summarizing, the machine not only provides for changing sequence of computations as the master cards vary but also cause the repeat operation of the selected computation for as many detail cards as are passed through the machine.

This takes care of the varying requirements in accounting operations since in many instances more than one detail card would be passed through the machine in a group. In the following claims the term "master computation control means" refers to the AK relay to effect division and the AN relay to effect the

$$\frac{A \times B}{C}$$

computation. One of these is selected to change

the machine from a normal multiplying condition to another computing condition to effect one of the above computations. The "selecting means" controlled by the master card sensing means refers to the EA and EB and EC relays. The above identifies the elements described by the specially adopted terms used in the claims.

While there have been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

I claim:

1. A record controlled calculating machine which is adapted to compute factor data derived from groups of detail cards by different types of computations determined by interspersed master cards which bear distinctive designations for determining the type of computation to be performed, means for sensing the master cards to determine the computation selecting designation it bears, a plurality of master computation control means for conditioning the machine to effect one type of computation or for reconditioning the machine to effect another type of computation, each of said master computation control means including means controlled thereby to retain it effective during the computation effected under control of each of the following detail cards, selecting means controlled by said sensing means to render the related master computation control means effective for operation according to the computation selecting designation sensed on the master card, means controlled by said selecting means to render the selected master computation control means effective for operation for each of the detail cards following the master card which selects the computation, and means responsive to the sensing of a master card following the last detail card of a group for rendering the last named means ineffective when said master card bears a designation different from the preceding one, whereby the effective master computation control means is rendered ineffective.

2. A record controlled calculating machine which is adapted to compute factor data derived from groups of detail cards by different types of computations selected by master cards interspersed with the groups of detail cards, said master cards having distinctive designations for determining the type of computation to be performed, a plurality of master computation control means for conditioning the machine to effect one type of computation or to recondition the machine to effect another type of computation, means for sensing the master cards to determine the type of computation selection designation it bears, selecting means controlled by said sensing means and responsive to the particular designation sensed thereby for accordingly rendering the related master computation control means effective for operation, and means controlled by the selecting means for the selected master computation control means for retaining the selected master computation control means effective for operation to continue the same type of computation for the detail cards following the master card which effects its selection.

3. A record controlled calculating machine which is adapted to compute factor data derived from groups of detail cards by different types of computations determined by master cards interspersed with the groups of detail cards, said master cards having distinctive designations for determining the type of computation to be performed, a master computation control means for changing the condition of the machine in which one type of computation is effected to another condition in which another type of computation can be effected, means for sensing the master cards to determine the type of computation selection designation it bears, means controlled by said sensing means and responsive to a particular designation on the master card sensed thereby for accordingly rendering the master computation control means effective for operation, means controlled by the said last named means for retaining the master computation control means effective for operation to continue the same type of computation for the detail cards following the master card, and means responsive to the sensing of a master card following the last detail card of a group and bearing a designation different from the one which caused the master computation control means to be effective for rendering said last named means ineffective.

4. A record controlled calculating machine which is adapted to compute factor data derived from groups of detail cards by different types of computations selected by master cards interspersed with the groups of detail cards, said master cards having distinctive designations for determining the type of computation to be performed, a plurality of master computation control means for conditioning the machine to effect one type of computation and to recondition the machine to effect another type of computation, means for sensing the master cards to determine the type of computation selection designation it bears, selecting means controlled by said sensing means and responsive to the particular designation sensed thereby for accordingly selecting the related master computation control means for operation, means controlled by the selecting means for the effective master computation control means for retaining the selected master computation control means effective for operation to continue the same type of computation for the detail cards following the master card which effects its selection, and means responsive to the sensing of a following master card bearing a different designation than the preceding one for rendering said last named means ineffective.

5. A record controlled calculating machine which is adapted to compute factor data derived from groups of detail cards by different types of computations selected by master cards interspersed with the groups of detail cards, said master cards having distinctive designations for determining the type of computation to be performed, a plurality of master computation control means for conditioning the machine to effect one type of computation and to recondition the machine to effect another type of computation, means for sensing the master cards to determine the type of computation selection designation it bears, selecting means for said master computation control means, means controlled by said sensing means and responsive to the particular designation sensed thereby for accordingly rendering the associated selecting means effective, means controlled by the effective selecting means

for rendering the related master computation control means effective for operation, means controlled by the effective selecting means for retaining the selected master computation control means effective for operation to continue the same type of computation for the detail cards following the master card which effects its selection, and means responsive to the sensing of a following master card bearing a different designation than the preceding one for rendering the effective selecting means ineffective and thereby said last recited means ineffective.

6. A record controlled calculating machine which is adapted to perform either of two types of computations controlled by factor data under control of detail cards only and which are arranged in groups and are passed through the machine in succession, each of said groups of detail cards being separated by distinctive master cards, and said master cards having identifying designations at differential locations to determine the type of computation to be performed under control of the following detail cards, a plurality of master computation control means to condition the machine to perform one type of computation or to differently condition the machine to perform another type of computation, means for analyzing said factor data on a detail card, and means for concurrently sensing the identifying designation on a following master card, a plurality of setup means controlled by said sensing means and selectively set thereby to select the related master computation control means for operation, and including means controlled by the setup means set up to retain said setup means set up during computing cycles in which a previously selected computation is being performed under control of a preceding detail card, and for breaking down the setup of the effective setup means before the sensing of the following master card to condition the setup means for a possible repeat setup when the next master card is sensed.

7. A record controlled calculating machine which is adapted to perform either of two types of computations controlled by factor data under control of detail cards only which are arranged in groups and are passed through the machine in succession, each of said groups of detail cards being separated by distinctive master cards, and said master cards having identifying designations at differential locations to determine the type of computation to be performed under control of the following detail cards, a plurality of master computation control means to condition the machine to perform one type of computation and to differently condition the machine to perform another type of computation, means for analyzing said factor data on a detail card, and means for concurrently sensing the identifying designation on a following master card, a plurality of setup means controlled by said sensing means and selectively set thereby, means controlled by the setup means set up to retain said setup means set up during computing cycles in which a previously selected computation is being performed under control of a preceding detail card, and for breaking down the setup of the effective setup means before the sensing of the following master card to condition the setup means for a possible repeat setup when the next master card is sensed, a plurality of supplemental setup means, one for each master computation control means, each of which includes means controlled thereby to retain it in setup condition, means controlled by the first named setup means while retained in setup con-

dition for selecting the related supplemental setup means, means controlled by the setup supplemental setup means for selecting the related master computation control means and rendering it effective for operation, means controlled by the selected master computation control means for retaining it effective for operation during the computing cycles in which computations are effected under control of a detail card following the master card which selected the computation, and means responsive to the sensing of a following master card during the analysis of the detail card which controls the selected computation and which bears a designation to select a different type of computation for terminating the setup condition of the effective master computation control means and the related supplemental setup means.

8. A record controlled calculating machine with card reading means, and card handling means for feeding in card cycles cards consisting of detail cards arranged in groups and interspersed by master cards bearing designations at differential positions for determining the type of computation to be effected under control of the following detail cards analyzed by the card reading means and effected in subsequent computing cycles, a punching mechanism of the column-by-column punching type and having a tray to receive cards fed by said card handling means from the card reading means, which cards are thereafter automatically fed endwise onto a carriage of said punching mechanism and to an initial result recording position and including means to effect the step-by-step escapement of said carriage from said result recording position, means for sensing said master card designations within a card cycle, a plurality of setup means controlled by said sensing means and selectively set up at differential times to determine the type of computation to be effected under control of the following detail cards, means controlled by the selectively set setup means for retaining it set up from the time it is differentially set up, through the subsequent computing cycles, and within the following card feed cycle in which the master card is fed to the punching tray of the punching mechanism, supplemental setup means commonly set up under control of each of the aforesaid plurality of setup means and including means to retain the supplemental setup means set up until the card is positioned to an initial recording position, and means controlled by the aforesaid supplemental setup means and responsive to the position of the card at said initial result recording position for effecting the operation of the means to initiate and effect the automatic step-by-step escapement of said card carriage whereby said master card is idly fed from the initial result recording position through said punching mechanism.

9. A record controlled calculating machine with card reading means and card handling means for feeding in card cycles cards consisting of detail cards arranged in groups and interspersed by master cards bearing designations at differential positions for determining the type of computation to be effected under control of the following detail cards, a punching mechanism of the column-by-column punching type, and in which form of calculating machine a master card is automatically fed by said card handling means from said card reading means into a card receiving tray of said punching mechanism, the presence of which card effects the power drive of said

card carriage to position the card to an initial result recording position during cyclic operations of said machine, and said punching mechanism including means to effect the escapement of said carriage step by step from initial recording position, means for sensing the computation selection designations of said master cards during a card cycle, a plurality of setup means set up at differential times in said card cycle to determine the type of computation to be performed under control of the following detail cards, means controlled by the selectively set setup means for retaining the setup means set up from the time it is differentially set up to a subsequent card feed cycle and within the subsequent card feed cycle, supple- 15

10 5 mental setup means commonly set up within the subsequent card cycle and under control of each of the aforesaid setup means and including means to retain said supplemental setup means set up within said cyclic operations of the machine, and means controlled by the aforesaid supplemental setup means and responsive to the position of the card carriage at the initial recording position to initiate the operation of said carriage escapement means to effect the automatic step-by-step escapement of the card carriage whereby said master card is idly fed from the initial result recording position through said punching mechanism.

ARTHUR H. DICKINSON.
